UNITED STATES PATENT OFFICE.

JOHN D. PEDERSEN, OF JACKSON, WYOMING.

FIREARM.

1,072,982.

Specification of Letters Patent. Patented Sept. 9, 1913.

Application filed November 11, 1912. Serial No. 730,557.

To all whom it may concern:

Be it known that I, JOHN D. PEDERSEN, a citizen of the United States, residing in Jackson, in the county of Uinta and State 5 of Wyoming, have invented certain new and useful Improvements in Firearms, of which the following is a specification.

This invention relates to magazine firearms, and more particularly to breech-loading firearms of the slide-action class.

The object of the invention is to provide improved devices and combinations of mechanism whereby center-fire, high-power cartridges may be rapidly and more safely 15 passed or transferred from the magazine and into the loading chamber, ready for delivery into the barrel of the firearm.

For illustrating my present improvements, I have herein shown them adapted 20 and applied to the mechanism of the left-hand slide action fire-arm which is described in the Letters Patent of the United States, No. 963,171, granted to me July 5, 1910, to which reference may be had for a more detailed description of those features of the mechanism which are not mentioned herein, or which, although mentioned, are not herein fully described. In that patent, the mechanism of the firearm is represented as being 25 arranged and fitted for using rim-cartridges of the center-fire kind, while in this application I have represented the mechanism as being fitted or adapted for using cartridges of the so-called rimless style, but having the same centrally located primers. The protection of the primer of one cartridge against accidental firing from contact with the bullet of the leading, or most rearward, cartridge, while this latter cartridge is being 30 transferred from the magazine into the barrel of the firearm, is a principal object of my present invention; other objects and features are set forth in the following description.

For convenience in describing the mechanism of the firearm, this may be considered 45 as comprising a breech-mechanism which mainly consists of two principal mechanisms, of which one is the breech-block mechanism and the other, the action-mechanism. The first of these two mechanisms in the form and arrangement thereof shown in the drawings, comprises the breech-block and the several details appertaining thereto; 50 and, the second said mechanism comprises a magazined action-bar with its cartridge-car-

rier or elevator, and the details appertaining thereto. These mechanisms are herein shown arranged in substantially the manner illustrated and described in my said prior 60 Patent No. 963,171, and to facilitate comparison, the corresponding details are herein usually designated (in a general way) by the same reference characters. In addition to the features above referred to, I have also 65 illustrated herein certain improvements comprising a sear-lock device and certain combinations in connection therewith, which constitute in part the subject-matter of my Patent 1,044,568, dated Nov. 19, 1912. 70

In the accompanying drawings, forming a part of this specification:—Figure 1 is a plan or top view of the receiver of the gun-mechanism and of the rearward portion of the barrel, some parts being broken away for 75 showing certain details. Fig. 2 is a sectional side elevation, showing the breech-block mechanism and the action-bar mechanism of the firearm, both being in the firing position. Fig. 3 is a sectional side elevation 80 similar to Fig. 2, but showing the mechanism with the details thereof in a relative position which they will normally occupy on the partial retraction of the block-mechanism by the rearwardly moving action-mechanism. This view shows an empty shell, as X, drawn back nearly to the position for 85 ejection through the side opening 39, as more fully described in my said prior patent. Fig. 4 is a view corresponding to the middle 90 portion of Fig. 3, for showing the parts directly involved in the retraction of a cartridge, and in the transfer of the same into the loading chamber forward of the retracted breech-mechanism; this view shows 95 a leading cartridge, X', initially elevated for the final elevation or transfer into the loading chamber. Fig. 5 is a view corresponding to Fig. 4, but showing the operation of transferring the cartridge advanced 100 slightly beyond the position shown in Fig. 4. Fig. 6 is a sectional side view similar to Figs. 4 and 5, for illustrating a more advanced stage in the cartridge elevating operation; this view shows the cartridge with 105 the head-flange, g', thereof overlapping the firing-point opening f in the breech-block 25. Fig. 7 is a view similar to Figs. 4, 5 and 6, and shows the cartridge-elevating mechanism in its extreme upper position, with the cartridge elevated into alignment with the bore 110 of the barrel 24. Fig. 8 is a view similar to

Figs. 4, 5, 6 and 7, but shows the operating mechanisms moved farther over toward their firing position, the leading cartridge being partially entered into the bore of the barrel; this view shows the next-following cartridge shifted upwardly, and there detained awaiting the further forward movement of the action-mechanism, while the retractor-elevator has resumed its idle or lower position. Fig. 9 is a view similar to the preceding Figs. 2 to 8, but shows the action-mechanism advanced nearly to its forward position, and indicates the breech-block mechanism as being in a corresponding position; this view particularly illustrates the manner in which the said next following cartridge, as X^2 , is delivered into position at the rear of the magazine-tube ready for retraction after the loaded-in cartridge, X' , shall have been fired. Fig. 10 is a sectional view in line Y—Y, Fig. 3, showing the parts at the left hand of said line as seen from the right hand thereof. Fig. 11 is a sectional view in the line Z—Z, Fig. 3, showing parts at the left hand of said line as seen from the right hand thereof. Fig. 12 is a side view mainly in section, and corresponding to a portion of Fig. 2, for showing the relations between certain features of the breech-block mechanism and of the action-mechanism at a moment just preceding the retraction of the sear-lock for permitting the firing of the loaded-in cartridge. Fig. 13 is a horizontal sectional view drawn in alinement with and above Fig. 12, for illustrating certain features of the breech-block mechanism; this view corresponds with Fig. 11 of my said prior Patent No. 963,171, and with Fig. 15 of my said prior Patent 1,044,568. Fig. 14 is a side view of the breech-block drawn in alinement with the same part in Fig. 12, the construction shown substantially corresponding with that illustrated in said prior patent, particularly in connection with Fig. 8 thereof. Fig. 15 is an enlarged view of the combined sear-lock-retractor and action-bar-lock 36, as seen from the left hand in Figs. 2 to 9 inclusive and in Fig. 12, represented in connection with certain parts indicated by dotted lines, as hereinafter more fully described. Fig. 16 is a fragmentary view of a portion of Fig. 12, showing the sear-lock mechanism in the same position as illustrated in Fig. 12, on an enlarged scale. Fig. 17 is a view the same as Fig. 16, excepting certain details are shown in a different position. Fig. 18 is a plan view on a scale corresponding to Figs. 15, 16 and 17, of the member 36 in the form and arrangement shown in those views. Fig. 19 is a plan view of the action-bar which constitutes the rearward end of the magazine action-mechanism, and which serves as a frame-work and carrier for the operating details, as illustrated in the preceding sectional side views,

and is hereinafter further explained. Fig. 20 is a vertical longitudinal sectional view of the action-bar shown in Fig. 19. Fig. 21 is a sectional view on the line J—J, Fig. 20, looking in the direction of the arrow on the said line J—J. Fig. 22 is a similar sectional view of the action-bar on the line J^1 — J^1 , Fig. 20, looking in the direction of the arrow on said section line. Fig. 23 is an end elevation of the action-bar as seen from the right hand in Figs. 20 and 24. Fig. 24 is a side elevation of the action-bar, and is drawn in alinement below Fig. 20 for convenience of comparison therewith. Fig. 25 is an end elevation of the action-bar, as seen from the left hand in Fig. 24. Fig. 26 is a plan view of the underside of the action-bar, as seen from below in Figs. 19 to 25 inclusive. Fig. 27 is a cross sectional view of the action-bar in line J^2 — J^2 , Fig. 20, looking in the direction of the arrow in said section line. Fig. 28 is a small detail view taken on the line J^3 — J^3 of Fig. 4, looking in the direction of the arrow on said line, for illustrating the relation of certain features of the cartridge-controlling devices in the action-mechanism, and for this purpose this figure is drawn at the right hand of and in alinement with the corresponding parts in Fig. 4, as indicated by the connecting dotted line 19. Fig. 29 is a sectional view in the line J^4 — J^4 , Fig. 5, looking in the direction of the arrow in said section line, for further illustrating the devices shown in Fig. 28, and in connection with the illustration of the same features in the preceding figures. Fig. 30 is a diagram or chart illustrating the movements of a cartridge following through the operation of the gun-mechanism, from the position shown at X^2 , Fig. 2, through the successive stages illustrated in Figs. 3 to 9 inclusive, and thence to the firing position shown at X in Fig. 2; the path of travel of the center of the cartridge-head through the successive positions being indicated by the dotted line 20, in the case of a cartridge of the proportions herein shown and when used in a mechanism also substantially of the proportions herein shown, and referring to the movements of the cartridge in the gun-mechanism considered as a whole. Fig. 31 is a diagrammatic view corresponding to a portion of Fig. 30, but indicating by dotted line 20^a, the normal path of movement of the center of the cartridge-head in and with relation to the action-bar, and to the forward face of the breech-block.

Similar characters designate like parts in all the figures.

Such reference characters as are shown in the drawings and are not mentioned herein, will be found described in my said prior patent in connection with features not essentially or fully involved or included in the subject-matter of this application.

The parts shown herein, and which are or may be the same, or substantially the same as illustrated and described in my said prior Patent No. 963,171, comprise the following: The frame or receiver, 21, and its interior space and guiding surfaces for the block-mechanism (including the recoil abutment 26) and for the action-bar; the butt stock and its attaching means; the barrel, 24; the action-bar 27, with its tubular magazine, and excepting the block-actuator portion thereof, herein designated in a general way by B; the trigger plate 22, and its attaching means; the trigger 46, pivot 48, guard 70, and safety-lock 71, with their minor details; the magazine-spring 50, follower 51, and the cartridges, as X, supplied thereby to the loading mechanism; the extractor, 29, and the means for supporting and operating the same; the rearward end portion of the cartridge carrier 60, its pivot, 61, and its actuator device 65, with their details and appurtenances; the loading door 52, (except as to the upper surface thereof) with its opening 52^a, and the pivot and spring therefor; the slideable breech-block, 25, with its cartridge-holding grooves and lips,—cams and shoulders,—its locking face 25^a, and the means for engaging or carrying the several operative parts,—except as to certain features hereinafter described and not shown in said patent; the firing-pin, 30, with its sear-catch, actuator 37^a, lock-pivot 35, main-spring 33, and sear-pivot 32; the sear, 31; the reciprocatory inertia-member, as 37, with its connected shell-ejector, 40, and its operative connection at 36^a with an arm of the action-bar lock; and the device, as 38, for manually disengaging the action-bar lock.

In this application, in place of the action-bar lock 36 of said prior Patent No. 963,171, I have herein shown substituted therefor a combined action-bar-lock and sear-lock-retractor, which is described in my said Patent 1,044,568, and is herein also designated in a general way by the reference number 36. As in said prior application, the slideable breech-block, 25, is herein shown fitted to receive a firing-pin member, 30, which is arranged to slide therein, and with the sear, 31, and the action-bar lock, 36, both operatively-supported thereon and located between the depending side-walls of the block. For directly co-acting with these two members 31 and 36, and for indirectly but positively co-acting through these members with the firing-pin and other members, I have herein shown the rotatively-retractable sear-lock, k, supported on a pivot k¹, and having the lock-face k², actuator bearing-face k³, engaging actuator t, and the retractor-bearing-face k⁴. The sear, 31, and the sear-lock, k, with their actuators and connected details and the combined sear-lock-actuator and

block-actuator-lock, as involved in certain combinations of these parts in and with the breech-block mechanism, constitute in part subjects-matter which are set forth in my said Patent No. 1,044,568, in which I have more fully described and have claimed the same. The foregoing devices, however, are herein shown as constituting in part other subjects-matter not illustrated or described in my said prior application, but which are described and claimed in this application.

The term slideable is herein employed in respect of the breech-block and the breech-block mechanism, to designate any suitable forward and rearward movement thereof, such, for instance, as may in any given instance be found convenient for withdrawing that device or mechanism out of the loading-chamber; and this movement may be rectilinear or approximately so, or may in some cases be of a modified character, without departing from my present invention. The term upward, or upwardly, is herein applied to the movements of the cartridge elevating or transferring devices, and to other features, for indicating an upward movement or direction thereof when the firearm is located with the barrel about horizontal and above the magazine, this being, of course, the more usual position in which a firearm of the small-arm class is held for aiming and firing.

The action-mechanism, in a firearm of the class herein illustrated, being slideable with little resistance when very near its extreme forward position, if the cartridge in the barrel should be fired while this mechanism is slightly retracted, but not far enough to prevent the firing-pin reaching the primer, then a violent forward movement of this mechanism relatively to the frame would instantly take place from the recoil of the frame, with the result that the two rearward cartridges in the magazine would be driven together with a heavy blow which would be liable to fire the forward said cartridge, and would possibly deform the head of the rearward cartridge to the extent of rendering this cartridge unusable, and so block the further operation of the firearm. For the purpose, among others, of preventing such an accidental or irregular operation, I have devised a system of locking devices, the co-actions or effects of which extend through the entire train of operative-mechanism; this system comprises a plurality of locking devices which are arranged in part in the action-mechanism for positively controlling the rearward cartridge in the magazine, and in part in the breech-block-mechanism, for holding the sear located against retraction from the retracted firing member until after the action-bar shall have been positively locked in its extreme forward position, for thereby pre-

70

130

venting the direct operation of the action-mechanism from the initial stage of the recoil, and also thereby preventing such an improper operation of this mechanism from interfering with the proper operation and control of a cartridge located in the rearward end of the magazine. Thus, for supplementing and extending the devices and combinations of mechanism as set forth in my said prior patent, my present invention comprises or provides two locking members, one of which is applied to the breech-block-mechanism for locking the sear into engagement with the firing member, and the other of which is applied to the action-mechanism for locking the rearward cartridge into engagement with an elevator or transfer device comprised in this mechanism. For co-acting directly with the sear-locking device, I have provided a retractor therefor, which also is carried on the breech-block mechanism and is arranged in a combination with the action-bar lock; and is also arranged for operation in alternate directions by the corresponding alternate movements of the reciprocating firing-member in the breech-block. Similarly, for co-acting directly with the cartridge locking device, I have provided a guide-stop device which is located on the frame and is arranged for operation in alternate directions during corresponding reciprocating movements of the action-mechanism.

On firing the charge, the first effect is, of course, the recoil of the frame and the rigidly connected parts, including the breech-block and its complement of operative members, which all move back together. Owing to the inertia of the action-mechanism, and the slideable manner in which this is supported by the frame, the first effect of the recoil is, evidently, to hold this mechanism forwardly relatively to the frame; but on the re-action, or counter-recoil, instantly following the primary recoil, the action-mechanism, as I apprehend, tends first to move backwardly and then to move forwardly relatively to the frame. These violent and intense alternating recoil-actions take place so quickly that in some cases,—especially while the firearm is in some unusual position,—all the cartridges would be driven forwardly in the magazine-tube during the initial back-stroke of this tube, were not means provided for effecting the prior retraction-engagement of the rearward cartridge with some part of the action-mechanism; and for the same reasons, the leading cartridge might possibly be disconnected from that engagement were not means provided for positively maintaining said engagement during the earlier stages of the recoil and reaction. And when such means are provided for both of those pur-

poses, there may still occur a similar separation or forward movement of some cartridges away from the positively held leading, or rearward cartridge, with the result of causing the point of said first or leading cartridge to strike a heavy blow against the head of the second, or following cartridge, and should this blow come upon the primer, said following cartridge might thereby be prematurely exploded while in the magazine. This danger, which is largely increased by the more recent and greatly extended use of high-power explosives and sharply pointed steel bullets, is effectively provided against by those features of my present improvements whereby the leading cartridge, while being placed in said retraction-engagement, is shifted to and positively held in the offset and inclined position which is herein designated as the primer-safety position.

The complete mechanism in the form herein illustrated, comprises three principal reciprocatory mechanism-components, the breech-block mechanism, the guide-stop device, and the magazine action-mechanism which actuates the other two of these components. The action-mechanism is slideable below the barrel, and in part below the breech-block mechanism, with which it connects for operating the same rearwardly out of, and forwardly into, the loading-chamber in the frame at the rear of the barrel. Alongside of the action-mechanism and forward of the loading-chamber, the guide-stop device is supported on the frame, preferably for rearward and forward movement and preferably for sliding movements. When movably-supported, this guide-stop, as D, may be operated by guide-actuating faces, as 12 and 12^a, (Figs. 19 and 20) suitably located on the action-bar 27, this bar being the frame of the action-mechanism. The stroke of the action-mechanism is in excess of the stroke of the breech-block, and this has a stroke in excess of the length of the cartridge, while the reciprocation of the guide-stop is relatively short, and its forward stroke takes place after the completion of the forward stroke of the breech-block, and during the forward movement of the action-mechanism relatively to the breech-block. When the action-mechanism is slid rearwardly for retracting the breech-block mechanism the full length of the cartridge, the relatively large space or chamber thus formed forward of the breech-block and rearward of the barrel, and above the retracted action-bar and the magazine tube therein, constitutes the loading-chamber, and is designated by R in Figs. 4, 5 and 6.

By the term magazine, and magazine-tube as herein employed, I refer to the bore or chamber in the action-mechanism, and which is located, preferably and for con-

venience, below the barrel, and in which the supply of cartridges is stored or held in reserve. This bore as 9, Fig. 3, extends forwardly from near the rearward end of the action-bar to or nearly to the front end thereof. The forward part of this magazine or chamber may, in practice, be conveniently supplied by using a tube-extension, as 9^a, fixed in the forward end of the action-bar 27. Thus the magazine may be said, in a reverse order, to extend from near the front end of the said tubular-part 9^a rearwardly to the transverse wall or stop-face 3^a, at the rearward end of the leading cartridge X¹, when this is in the retraction-position indicated in Fig. 2.

The arrangement and mode of operation of the mechanism, in a general way, particularly of those parts and details shown in my said prior Patent 1,044,568, may be briefly described as follows:—The spring-actuated firing-member, 30, when retracted, is held by the catch 31^a on the sear 31 engaging with the sear-catch 30^b, and is disengageable by a suitable trigger, as 46. On firing a cartridge, the recoil operating through the inertia-block 37 and its connection with the arm 36^a, acts in a forwardly direction to turn or oscillate the member 36 on its pivot 35 and retract the bearing face 36^b of said member 36 away from the sear-lock *k*, which thus becomes operable by its actuator *t*, for locking the sear. Thus the breech-block mechanism comprises two sear-lock actuators, (as *t* and 37^a) which operate on the sear-lock, the one (*t*) directly and continuously, and the other (37^a) indirectly and intermittently. The actuator 37^a is normally of greater power than the device *t*, and is operated into active relation with the lever-arm 36^a by the backward stroke of the firing-pin member. When the sear-lock *k* is retracted (Figs. 2 and 17) it is held in this position by the retractor-arm until this device shall itself be shifted into its own retracted position, Figs. 3, 12 and 17. This retraction of the sear-lock-retractor is directly effected by the forward stroke of the firing-member. By this means the sear-lock is released and allowed at once to assume a normally engageable position relatively to the sear on the firing-pin nearing the forward end of its stroke. The member 36 is operatively-intermediate between the sear-lock and the firing-pin member, and also between the sear-lock and the block-actuator B, of the action-bar, and also between the sear-lock and the entire block-mechanism, and the shiftable guide-stop member D, which is hereinafter more fully described.

The actuator B, during its rearward stroke relatively to the block 25, constitutes combined in one device, a firing-pin retractor and a retractor for the sear-lock-retrac-

tor. In this two-lock safety-device, the lock-action-timing means is operable by the co-action of the block-actuator and the transmitter-connection for retaining the sear in locked position until this block-actuator and the guide-stop D have been locked in firing-position. The breech-block 25 has an extended longitudinal movement in the "receiver," 21, and at its forward end has an upward movement into engagement with a frame abutment 26, and has a downward movement for disengaging its face 25^a from such frame abutment. These movements are imparted to the block 25 by the action-bar 27, the rearward end of which has inclined faces and other details (also more fully described in my said patent) whereby this part of the action-bar serves as the block-actuator for both the longitudinal and the upward and downward movements, and thus serves at the end of the forward stroke as a block-lifting device or block-placer, and at the beginning of the rearward stroke thereof as a block-depressing device, or block-releaser.

The normal position of the sear-lock-retractor at the moment after firing a cartridge, is shown in Figs. 12 and 16. At this time the sliding member 30 is in its extreme forward position in the block 25, and the lock 36 has its forward lever-arm 36^m below the guide-surface or stop-face 27^a of the block actuator B, which is thus left free to be slid rearwardly by the operator, as in Fig. 3. On this movement taking place, the block-actuator B first passes over the lock-arm 36^m, and depresses the block out of engagement with the recoil abutment 26, said lock-arm 36^m being held in said downward position until the block-actuator B again goes forward and elevates the block into engagement with said recoil abutment, as in Figs. 2 and 12. When the forward movement of the member B is fully completed, the face 27^a passes forward of the lock-end 36^m (see Fig. 12), which is instantly forced up rearwardly of the block-actuator B, and also instantly retracts the sear-lock *k* from the sear, and thereby permits the sear to be withdrawn from the firing-pin. Thus the member B operates not only as the block-actuator but also operates to time or delay the retraction of the lock *k* until after this block-actuator has been itself placed and locked in the firing position. The block-actuator, B, is also the firing-pin retractor, since on the back stroke thereof, its face 27^a bears against the retraction-face 30^c of the firing-pin 30, and so retracts or slides backward that member in the block 25, and the face 27^a thus constitutes a safety-stop against which the firing-pin will strike if thrown forward at any time before said face 27^a passes forwardly out of the range of movement of said face 30^c.

After the retracted firing-pin is caught by the sear, and the block 25 has gone forward, the block-actuator B is then in full engagement with, and ready to begin the elevation of the forward end of the block. At this time, the forward end 36^m of the combined actuator and lock 36, is still engaging under the inclined guide surface at 27ⁿ on actuator B, and is thus held with its opposite end 36ⁿ retracted out of engagement with the sear-lock k (Figs. 3 and 16,) notwithstanding that at this time the actuator 37^a has gone to a position rearwardly of the pivot 35. As the block-actuator B is now drawn forward, this contact of arm 36 on the guide 27ⁿ keeps said arm retracted until after the forward end of the block is fully placed into its firing position shown in Fig. 2. During the last part of this forward movement the retractor 5 on the elevator 60 normally engages the then leading-cartridge, and the actuator B draws off from the lever-arm 36^m (Fig. 12), and then passes beyond the range of the firing-pin stroke (Fig. 2); this permits the actuator 37^a instantly to operate the member 36, which then assumes its position in Fig. 17, where it has retracted the sear-lock, k, out of engagement with the sear-lock catch 31^c, and reset the inertia-member 37 in its rearward position ready for being operated by the recoil, and permitting the fire-arm to be fired. On pulling the trigger, the firing-pin goes forward and fires the cartridge, being permitted to do this by the actuator face 27° being in the forward position shown in Fig. 2. This operation of the firing-pin carries the actuator 37^a forward of the pivot 35 and thereby throws down the lock-end 36^m of the member 36, so that this lock-end will pass under the said guide-surface 27ⁿ on the next backward movement of actuator B; and at the same time the rearward arm 36^m of this member 36 is retracted out of engagement with the sear-lock k, which thus becomes engageable again with the sear when the proper moment arrives therefor. The entire cycle of operations may now be repeated as before.

The block-actuator B, simultaneously holds the sear-lock-retractor in its retracted position while pushing back the firing-pin, and continues these concurrent functions until it has pushed the block-mechanism back to the point where the member 37 forcibly meets a suitable frame abutment; the actuator B thus operates directly on the sear-lock-retractor and operates indirectly through the block itself for concurrently acting positively upon the sear-lock-retractor by the reaction of and from the fixed frame-abutment. Since the member 37 is also the ejector-actuator, (in connection with said abutment,—see said prior patent)

that positive retraction of the sear-lock-retractor, the positive action of the shell ejector when the block reaches its fully retracted position, the maintenance of the compression of the transmitter-connection between the firing-pin and said sear-lock-retractor while this is itself retracted, and the locking of the sear into engagement with the firing-pin, all occur at the same time, on or by the full completion of the rearward stroke of the actuator B in the fire-arm, and relatively to the breech-block and simultaneously with the retraction-elevator bringing a cartridge into transfer position below the loading chamber, as herein-after more fully explained.

When the mechanism is in position for firing, and should it then be desired to withdraw the unfired cartridge, the operator by pressing on the plunger 38 moves forward the inertia-member 37, and through the arm 36^a shifts the member 36 for at once unlocking the actuator B and releasing the sear-lock k, which thereupon locks the sear so the firing-pin cannot be released. The actuator B may now be retracted and the block 25 operated to withdraw and eject the unfired cartridge. In this application I have used the terms firing-pin and firing-member as referring to the member 30 or to some form of device suitable for use in lieu thereof.

If by any means, when the action-bar is near the end of its rearward stroke, the sear becomes unhooked from the member 30, then this member may be thrown forward by the main-spring 33, and bear against the actuator B, and so cause an undue pressure upon the inclined draft-face c' during the entire period of the upward operation of the cartridge-lifter 60. The retraction of the sear-lock-retractor 36 secures the free action of the sear-lock at that precise moment, and thereby permits the sear to be effectively locked against such an accident. Should the force of the main-spring be thus transmitted to the draft-face c', the inclination of this face would produce an upward pressure of the block 25, and a downward pressure of the actuator B, against their respective guide surfaces in the frame 21, and so create a frictional obstruction to the free and proper operation of the action-bar during the operation of the cartridge-lifter 60, and thereby cause wedging together of those sliding members, preventing their proper operation, and also preventing the operator from being able to judge by feeling as to the manner of the action of the mechanism. Furthermore, should the firing-member 30 be allowed to follow forward against the actuator B, on the final part of this actuator movement, the upward shifting of the block 25 into its locked or firing position, (Fig. 2) would allow the firing-pin point, 30^t, to come

into direct contact with the cartridge primer, and thus endanger the safety of the cartridge. In the usual rapid action of the mechanism, that small final movement occurs in an extremely small fraction of a second, and this would permit the firing-pin to approach the primer with a dangerous velocity and power. But by means of the described organization of the sear-lock and its retractor, and of the compound retractor-elevator as herein combined with the action-mechanism, and with the block 25 and the sear and firing member, those accidental results are effectively prevented.

During the rearward movement of the magazine, as above indicated, the fresh cartridge X^1 , Fig. 3, then at the rearward end of the magazine-tube, has been drawn backwardly into a position under the loading chamber, and when the action-mechanism is started forward from its extreme rearward position, (in which the firing pin will have been fully retracted and engaged with the sear,) the main elevator-member 60 engages over the elevator-actuator 65 and comes to the position indicated in Fig. 4, where the further forward movement of the action-mechanism will cause said actuator 65 to carry the main elevator member 60 upwardly, and thus gradually elevate or transfer the cartridge from the retracted position at X^1 , Fig. 4, to the position shown at X^1 , Fig. 7, where the cartridge is fully elevated and is in engagement with the forward end of the breech-block ready for being carried forwardly in the bore of the barrel 24. After this, and during the further forward movement of the action-mechanism, the forward end of the breech-block mechanism is elevated into full engagement with the abutment or recoil face 26, (Figs. 2 and 12) and thereupon the action-bar lock 36 is thrown upwardly for locking the action-mechanism, and also the movable guide-stop D, in the forward position while the rearward end 36ⁿ of sear-lock-retractor 36 simultaneously retracts the sear-lock and thus leaves the mechanism in condition for firing, as in Fig. 2. This operation of the mechanism follows, it will be seen, the description thereof which is given in said prior patent, and in said pending application, as to such features as are therein illustrated. I will now explain more in detail regarding the organization, functions, and modes of operation of certain features and combinations which are comprised in my present improvements.

As regards the functions of some details and features of the action-mechanism,—especially as to the guide-stop and the retraction-elevator and certain combinations therewith,—the breech-block mechanism, although in some respects of a complex character, may be considered as a single element of a more comprehensive or extended combination, and

hence in some instances I have designated that compound element as the sear-lock block-mechanism, this being provided with some suitable sear-lock-retractor which is operated by the combined block-actuator and sear-lock-retractor actuator. This actuator, which is a part of the action-mechanism, may have, as herein illustrated, a working stroke considerably in excess of that of the block-mechanism, and be so arranged that the sear-lock-retractor is in its retracted position throughout the working stroke of the block-mechanism and is only released during the excess forward stroke of the action-mechanism, and after the completion of the forward stroke of the block-mechanism.

As in said prior patent, the upper tube-wall of the magazine is shown provided at the rearward end with a cartridge outlet side-opening 55, corresponding in location with the transfer position, or elevation-position, of the cartridge. In its retraction-position, X^1 , Fig. 2, the cartridge extends a short distance back of the groove 3^a, this being located rearwardly of the projections 55^a and 55^b which extend inwardly from the sides of the magazine (Figs. 19, 20, 22) and which then stand directly above the rear end of the barrel or body portion of the cartridge shell. On the preliminary lifting movement of the cartridge, this moves upwardly, and moves forwardly in the magazine, from its retraction-position in Fig. 2 to its elevation-position in Fig. 4, thereby bringing its head-groove into alignment with said guide-projections 55 and 55^a, and so on the further elevation of the cartridge, these projections enter the head-groove and hold the cartridge in positive engagement with the action-bar until after the continued upward movement brings the cartridge also into similar positive engagement with the similar projections 25^c on the breech-block. The said projections or guides, 55^a, 55^b, are preferably extended downwardly (Figs. 8, 22) to a distance which brings their lower ends directly forward of the cartridge flange g' before this comes fully up to the elevation-position, so that when this flange moves upwardly and forwardly as described, and before this movement is completed, these guides enter the head-groove and are thus in position for engaging the forward face of that cartridge flange, g' , in the most direct and effective manner. This operation of the cartridge is further safe-guarded by the continuing during such rearward movement of the positive engagement of the retractor-lifter 5 with the lower side of said flange g' of the cartridge X^1 . Thus the retractor-lifter by reason of its position and the inclined direction of its first upward movement, guides and regulates, or restricts, the described movement of the cartridge-head, and tends to prevent

any accidental throwing forward, whether by shock or otherwise, of the cartridge before this comes into locked engagement with said guides 55^a and 55^b; or with one of these 5 guides, in case one of them shall be omitted, as may be done in some instances.

In the magazine-tube 9 I have shown portions of the interior surface shaped, located and arranged for operating on the cartridge 10 after the manner of guides, whereby to offset the cartridge when this is in the retraction-position, and thus locate and support this 15 rearward, or leading cartridge out of alinement with the magazine axis, and also, preferably, at an inclination to this axis. As 20 shown in Fig. 2 for instance, the cartridge X¹ is elevated by the raised surface at 8, and is inclined by the combined action of this and other guiding surfaces or areas, especially by the depresso-guide 3 aided by the point-pressure derived from the usual magazine-spring. The said guide surfaces are, it will be noted, arranged one of them, as 8, below the outlet opening 55. When the 25 action-bar is forward, the surface 8 is also located above the lower line of the tube-wall 9, and at a distance from the axis of the tube which is less than the tube radius. Thus the magazine inner tube-surface may be said 30 to have, adjacent to the outlet opening, inwardly-extending cartridge-inclining areas arranged for offsetting and guiding the leading cartridge, as X¹, out of alinement with the following cartridge, as X², for bringing 35 the point of the one to bear in the safe-zone of the head of the other cartridge, as in Fig. 2. A further feature is that these cartridge-locating surfaces are arranged in successive positions circumferentially of the 40 magazine, and also longitudinally thereof, and are so arranged that the leading cartridge is inclined and offset while the magazine is in its forward position, and is thus maintained in that primer-safety position 45 (Fig. 2) during the rearward movement of the action-bar and until the cartridge reaches the transfer-position below the loading chamber R. One feature of my invention, therefore, relates to the combination 50 in and with the magazine-tube and its outlet opening, and with other elements elsewhere herein more fully set forth, of inwardly-extending cartridge-locating surfaces which are so shaped, located and arranged as to 55 operate on the most rearward and the next following cartridges in the tube, and by offsetting and inclining one said cartridge relatively to the other and relatively to the tube, to bring the said rearward cartridge into a 60 primer-safety relation or position against said next following cartridge, while the magazine is in its forward position; and to hold these cartridges in such relative primer-safety position during the retraction 65 of the magazine through the distance of at

least one cartridge-length. Also, this organization of the tube and those primer-safety guide surfaces or bearing faces, is supplemented and extended by the initial lifting-face 8^a and by the lifter-face 5^b and 70 the retraction-face 5^a of the compound retractor-elevator, so that the faces and surfaces of the two members 60 and 5 of this elevator, coöperate with the guide-stop D and also with the other said cartridge-positioning guide faces of the magazine. 75 Thus the leading cartridge X¹ is held in primer-safety position before and during its retraction to the loading position, by the co-action of guide-faces of which a portion of 80 them are furnished by the members which are, later in the operation of the firearm, to act for transferring such cartridge out of the magazine.

During the latter part of its forward 85 stroke, the action-bar 27 brings the guide-stop D to its forward position adjoining the depresso-guide 3 (Fig. 2) and does this in advance of the upward movement of the arm 36^m of the sear-lock-retractor 36, so 90 that the leading cartridge X², Fig. 9, will be shifted by the action of those guides and the magazine-spring, into the primer-safety position while the sear continues locked with the retracted firing-member 30. Thus the 95 entire train of mechanism is brought under safety-control, and the proper safe-guarding of the leading-cartridge is accomplished, and especially against any shock from the 100 firing of the loaded-in cartridge, as X, Fig. 2.

A further and important practical result of the mechanism herein described is that, on firing the cartridge the action-mechanism may be instantly retracted by the operator 10 without the risk of having the rearward cartridge fail to properly follow. When about to fire, an operator while holding the gun will sometimes draw backwardly with the left hand on the usual hand-grip attached to the action-bar; and since this pull or tension is being exerted (in some cases, strongly exerted), at the moment of firing, and since the action-bar-lock is instantly released on and by the firing and the recoil, it follows that the action-bar sometimes 11 may, in practice, be drawn back in a substantially automatic manner, and with a suddenness and at a velocity which would leave the magazine cartridges far behind. 12 This kind of accident will, of course, be more frequent when the cartridges become sticky from rust and dirt thereon, and thus less freely movable by the magazine spring. If the rearward cartridge fails from any 13 cause to instantly and closely follow the reTRACTING action-bar, of course the next loading operation may be defeated, and so result in delay or danger. For overcoming 14 these objections, the cartridge-elevator has 15

been arranged not only to move with the action-bar but it is also arranged to be preliminarily engaged with the cartridge while the magazine is still in its forward position. 5 This lifter or transfer means operates for different purposes, respectively, at two different locations and at two different stages of the operation of the mechanism, first for positively engaging the leading cartridge, as 10 X¹, Fig. 2, and later, in a retracted position, Fig. 4, for initially lifting this cartridge. As a result of these features the magazine spring may be of less power than would otherwise be required, thus facilitating the 15 convenient replenishing of the magazine.

In the normal operation of the mechanism, and by reason of the relative positions on the main actuator B of the face 27^a, for holding retracted the sear-lock-retractor, 20 and the face 12 for forwardly actuating the guide-stop D, this guide member is set or moved forward fully to its said initial position (Fig. 2) simultaneously with the release of said sear-lock-retractor. Thus said 25 guide-stop D is reset in position for receiving and guiding the next following cartridge, and is so reset at the instant before the firing-member becomes releasable by the sear. And when the sear-lock-retractor is 30 also, (as shown in this instance) an action-bar-lock, the locking of the action-bar against retraction also occurs instantly the said movably-supported guide-stop reaches its said forward or initial position. The 35 guide-stop being thus moved or slid forward by the guide-actuating face 12 on the main actuator B, and since this is itself locked in its forward position by said action bar lock 36, therefore this lock 36 operates to also 40 lock the guide-stop in its forward position, and operates to do this concurrently with the retraction of the sear-lock. Another guide-actuating face, 12^a, is located to actuate the member D rearwardly. During the 45 operation of setting and locking the guide-stop in forward position, this guide and the lower, raised surface or guide-bearing 8 (in this instance on the loading-door 52) move forward together and in a direction opposed 50 to the action of the magazine-spring; and during this movement the cartridge, X², Fig. 9, normally slides and is guided rearwardly into the retraction-position, Fig. 2, and with the head-flange thereof locked 55 rearwardly of the retraction-face 5^a of the elevator device. Thus during this operation of receiving and locking the next following cartridge into proper retraction-engagement in the action-mechanism, this cartridge is 60 safe-guarded by the sear-lock and its retractor, against any undue shock which might otherwise be caused by the premature or accidental releasing of the firing member. The member 36 is, therefore, a combined 65 sear-lock-retractor, action-bar lock, and

guide-stop lock. The guide-stop, D, is also a cartridge-detainer, and is located, when the action-mechanism is in or near its forward position, in such a working position and relation to the head-depresser guide 3 in the magazine, that when the cartridge then under detension shall be released, the head of this released cartridge (which now becomes the "leading cartridge") will be guided below and free of the lower end of said detainer guide D, and thus be directed into the proper retraction position, Fig. 2. Thus said combined guide-and-detainer D operates at successive times in successive ways. One function is to detain, or stop, the rearward movement of a following-cartridge when the leading cartridge has been carried rearwardly to the initial transfer-line, or position;—see Figs. 3, 4 and 8,—another function is to guide the cartridge in the manner and at the time as above explained. 70 75 80 85

A further feature or function is to continue that initial guidance and control of the cartridge-head after this engages with the retractor-elevator member 5, and until 90 the rearward movement of the action-mechanism has attained such velocity that the cartridge, (as X¹, then in retraction-engagement therewith) will have acquired its full momentum and so will normally continue its full rearward stroke without danger of accident or undue strain. This continued guiding-action and the period during which the same may be properly or preferably maintained, will be evident from 95 a comparison of the successive positions of the mechanism and cartridges as illustrated in the drawings. In Fig. 9, the head has been depressed or guided downward, and in Fig. 2 has gone rearwardly into full engagement with the retraction-face 5^a of the elevator. In Fig. 3 the cartridge is shown retracted far enough to normally fully overcome its inertia, and also far enough for the actuator B to retract the firing-pin and the 100 sear-lock-retractor, and thereby safe-guard the cartridge against shock from a possible premature release of the sear, should the firing-pin become prematurely retracted relatively to the block 25. 105 110 115

The location of the guide-stop D just forward of the loading-chamber R, brings the guide-surface 10, (Fig. 2) directly opposite to and into direct co-action with the retraction elevator member 5 in the rearward part of the magazine bore 9, when the action-mechanism is forward, in firing-position. Thus said guide-surface 10 is located for holding the cartridge-head positively in engagement with said retraction-elevator prior to the retraction of the sear-lock, and during the period while the firing-member is retracted and the sear is locked into engagement therewith, as elsewhere herein more fully described. These fea- 120 125 130

tures are further illustrated in the chart, Fig. 30, showing the successive stages in the travel of the cartridge in the mechanism.

Normally, of course, the sear-lock-retractor 36 is engaged by the action-mechanism at the instant the retraction-face 5^a of this mechanism begins to retract the cartridge which is at that time under the positive control of said guide D. Should the firing-pin 30 now become fully retracted relatively to the block 25, the sear would engage the firing-pin catch 30^b and the sear-lock would be free to at once lock the sear into engagement with said firing-member. And should the action-mechanism be drawn back with extreme quickness at the moment when the firearm should receive a heavy shock rearwardly,—as by a blow for instance,—it is evident the combined frictional resistance and inertia of the block might result in cocking the firing-member before the block would be fully retracted, and before the leading cartridge had passed free of said guide D; this guide therefore, by thus co-acting directly with the action-mechanism while this acts on both the firing-pin and the sear-lock-retractor, safe-guards the cartridge against the conditions resulting from such a premature and abnormal operation.

For instance, if that premature retraction of the firing-pin should occur to the full extent relatively to the block 25 and while this block is held forwardly in the loading chamber by abnormal friction or forces, the sear will normally engage the firing-member 30 and so prevent the main spring from driving the block backwardly with violence when the action-bar overcomes the resistance of the block; but if that premature retraction of the firing-member should not be the full amount, evidently said spring will at once throw the block forwardly with great force the instant such abnormal resistance shall be overcome; but in this case, the guide-stop device D operates positively to hold the then leading-cartridge X¹ in locked engagement with the retraction-face 5^a until the proper co-operation of all those members is restored, and thus prevent such a failure of operation.

The depressor-guide 3 is shown located on the action-bar rearwardly of the flange-guiding channel 3^a, which is formed by and between the face-plane 3^b, (Fig. 20) and the rearward surface of the head-guide 55^a. This depressor-guide is also located in opposition to the retraction-face 5^a of the depressible elevator-member 5 and with a sufficient space between for receiving the head-flange g' of a cartridge, Fig. 2, whereby this flange or rim may bear rearwardly upon its upper side against said depressor-guide 3, and bear forwardly at its lower side against said retraction face 5^a, (Fig. 9) and whereby these relations of said guide and retraction-

face with the head-flange may, during the retraction, be continued (see Figs. 30, 31) and during the preliminary or initial elevation of the cartridge head from the depressed retraction-position in Fig. 2 to the transfer position. Thus supplemental elevator device 5 is depressible by said depressor-guide 3, which for this purpose acts through the head of the leading cartridge X¹.

Prior to fully reaching its rearward position in the action mechanism (Fig. 2), the cartridge-head normally should partially depress the supplemental elevator device 5, in order to secure a proper engagement of the head-flange with this device. The face-plane 3^b, it will be noted, corresponds in position with the face or front surface (Fig. 8) of the block 25, these two surfaces being substantially in the same transverse plane relatively to each other while the block is being drawn forwardly by the action-mechanism and during the entire operation of transferring a cartridge from the magazine into the loading-chamber,—see Figs. 4 to 9.

In the elevator-mechanism, when arranged in the preferred manner illustrated, the relatively long-radius elevator member, as 60, is arranged to swing from a point 61 rearwardly of the cartridge head, while the relatively short-radius elevator member, as 5, is arranged to swing from a point 6 forwardly of the cartridge head. And in the transfer-position, these members are so located that the face 5^a of said shorter member 5 is located just forwardly of the head-flange g' when the cartridge is in position for transferring to the breech-block mechanism. The upward swinging movements of each said elevator-member on its point of support is reversely of that movement of the other said member. And while the larger said member 60 is swung down, if the shorter said member 5 be then swung upward, said face 50 then comes substantially into alignment with the guide 55^a of the action-mechanism (Figs. 4 and 8); and if the said member 5 be then swung downward, said face 5^a moves rearwardly of said guides 55^a (Figs. 2 and 9). When the main elevator member 60 swings upwardly through an arc substantially greater than the arc of movement of the member 5 on its pivot 6, then the main elevator face at 4, by reason of its greater radial distance from its axis 61, moves upwardly faster and farther than said flange-engaging faces 5^a and 5^b, and thus the cartridge will be carried upwardly away from these faces 5^a and 5^b about the time the cartridge-flange g' reaches the lower ends of the block guides 25^c just after the position shown in Fig. 5. By reason of this manner of organizing those features of the mechanism, if during

that early portion of the transfer movement, the operator should (as he may readily do) reverse the movement even slightly of the action-mechanism, thereby lowering the elevator-members, the cartridge in falling downwardly for want of support will become reengaged with the face 5^a of the said member 5, and will thus be prevented from becoming released and misplaced in the mechanism, thereby effecting the important object of safeguarding the mechanism against accident from such cause.

In thus describing the normal operation of the retractor-elevator, it has been assumed that the cartridge would be first located in the inclined retraction-position illustrated in Fig. 2, but in practice it may sometimes occur that for some reason the cartridge may not at once be forced back fully to that position, but may be stopped just before the head-flange passes the face 5^b of the secondary elevator member 5. In this case, as will now be evident, the flange g' will ride along on that member which now becomes a spring-actuated presser device for forcing the cartridge-head upward into engagement with the flange-guide or guides 55^a, which then act to positively draw the cartridge backwardly with the action-mechanism, doing this, however, while the leading cartridge X¹ is located in a line as high or higher than the axis of the following-cartridge X², in about the position in Fig. 4. Thus the described preferred arrangement of the elevator-member 5 may have two different modes of operation, and perform a plurality of functions under varying conditions, respectively.

While the lifter 60 is carrying the cartridge head upwardly, the actuator B is holding the sear-lock retractor 36 in its retracted position, and thus the sear-lock is permitted to be engaged with the lock and sear into engagement with the now retracted firing member 30, which is thereby double-locked in its own retracted position in the block during the entire period of time in which the primer is passing upwardly (Fig. 6) past the firing-pin opening f in the block-face. Thus the primer is safeguarded during such upward movement against any accident occurring, whereby the point 30^c of the firing-member might project through said opening f and so intercept the cartridge flange.

The elevator device, when arranged and furnished substantially as herein set forth, constitutes a means for engaging and drawing backwardly a cartridge, and also constitutes in part the means for first inclining the cartridge into, and then holding the same in, the described primer-safety-position, prior to and during such backward movement. In Fig. 4, the cartridge X¹, is shown in its elevation-position, and in aline-

ment ready to be transferred upwardly by the main lifter 60 into the upper position shown in Fig. 7; and, it will be noted, the cartridge has in both of these views the same longitudinal position relatively to the block 25.

On the initial upward movement of the main elevator, 60, to the extent for normally bringing the main elevator-face 4 up to the shell of the cartridge, (between the positions in Figs. 4 and 5,) the inertia and frictional resistance tends to depress the supplemental elevator 5 relatively to said main elevator. This action results in applying to the uplifting or transferring of the cartridge, two forces of which one is relatively positive and is applied through the said face 4, while the other is a yielding or spring-actuated upward thrust which is applied through the lifting face 5^b of said member 5; and this latter action or spring-pressure is normally begun at the time the main member 60 begins to move upwardly, so that by the time said lifting face 5^b reaches its position in Fig. 4 the spring-pressure has already become effective under the head of the cartridge, and continues thus to assist in the transfer operation until the two co-acting elevator members 60 and 5 reach their positions in Fig. 5, by which time the head-flange g' has, or will usually have begun (or will be ready to begin) to enter the guide-channel on the front of the breech-block. Thus the transfer of the cartridge from its transfer-position into the loading-chamber, is effected by the concurrent operation of two thrust-forces, one relatively positive and other yielding, these forces being applied to the cartridge at two points in its length, and with the positively-acting force applied forwardly of a relatively yielding force or thrust which is applied directly to the cartridge head during the delivery of the cartridge out of the action-mechanism. This organization and mode of operation of the transfer-devices, is found to be peculiarly favorable for securing a reliable operation of the mechanism under a wide range of conditions and speeds of operation, and with the firearm in various positions.

A further feature of the operation of the magazine and elevator-mechanism, is that the two lifting-faces 4 and 5^b act in a succession which changes during this operation. When the rearwardly-moving cartridge arrives at the location for point-release, (Fig. 4) the spring-actuated or yielding lifting-face 5^b acts first, and later, on the beginning of the upward movement of the main elevator 60, acts concurrently with the positively-actuated or main lifting-face 4; and, afterward this main lifting-face continues to act after said yielding face 5^b becomes inoperative upon the cartridge.

Thus at the beginning the action of one lifting-face (the yielding face 5^b) is succeeded by the combined action of the two said faces 5^b and 4; and, later, this concurrent or combined action of the two said faces is succeeded by the continued action of the one said main lifting-face 4. In the complete operation, therefore, the described actions begin with the rearwardly-located and 10 spring-actuated supplemental lifting-face, and terminate with the forwardly-located and positively-actuated main lifting-face. A further feature of these successive actions or stages of the complete operation, is that 15 the lifting-action of the spring-pressure lifting-face 5^b is accompanied by the continued operation of the retraction-face 5, and that the action of said forwardly-located main lifting-face 4 is begun during 20 that continued co-action of said spring-pressure lifting-face with said retraction-face.

The cartridge-head g' is normally held in its said depressed initial position, Fig. 2, 25 by the rearwardly acting force transmitted to the point of the cartridge by the usual magazine-spring, and during the continuance of this action the head operates against the depressor-guide 3, and thus normally 30 holds the supplemental lifter 5 also in its depressed position; but on the release of the cartridge from such point-pressure at any time during the retraction of the actuator, the supplemental lifter (operated by the 35 spring 6^a of suitable power therefor) at once lifts the cartridge-head which is thereupon guided forwardly and upwardly into proper relation with the block 25 for being immediately thereafter carried up by the 40 main-lifter 60 into the position shown in Fig. 7, and then continues in this position during the remainder of that rearward stroke.

In moving upwardly from its retraction-position in Fig. 2 to its elevation-position in 45 Figs. 3 and 4, the face 5^a of the secondary elevator-member 5 passes forwardly across the line of the flange-guides 25^c and, as shown in Fig. 4, stands free of and slightly 50 forwardly of the head-flange. This leaves the cartridge for the moment in a free or unclamped condition favorable for the proper performance of the operation immediately to follow. On the beginning of the 55 upward movement of the primary elevator-member 60, the said face 5^a first swings or moves backwardly toward the head-flange, and so draws, or forces, the cartridge head back close to the guide face 3^b of the action-bar, and thus serves to positively locate the 60 flange g' in correct position at the moment the cartridge passes upwardly out of engagement with said secondary member 5. Thus, in the action-mechanism, and 65 relatively to the action-bar, said retraction-face

5^a has, first, a forward movement and, second, has a rearward movement; and these movements take place in succession, and by reversely swinging movements about the two axes 6 and 61 respectively; the first movement taking place before, and the second one after the beginning of the upstroke of the main elevator-member. 70

On its back-stroke the action-bar carries along with it the reserve cartridges, so that 75 the rearmost cartridge as X¹, Fig. 2, is then transported backwardly in and with the action-bar 27 until, on the first part of the forward movement of this breech-block (Fig. 4), the cartridge lies its whole length 80 back of the barrel 24, and directly below the then open space 55, through which the cartridge is to be elevated into the loading-chamber R forward of and in engagement with the block 25, ready for being forced 85 into the barrel, as in Fig. 7. During this latter operation the action-bar moves forward to its initial position (Fig. 2), but the cartridges, if any, now in reserve are held back by the follower 51 actuated by the 90 usual magazine spring, and are prevented from following further backward by the stop device, as 9, which is so located that the retractor-elevator when in its extreme 95 forward position will engage in the head-groove ready thereby to positively retract this cartridge, as X¹, on the next rearward movement of the action bar.

While the main transfer member 60 is in its retracted or lower position (Fig. 2), the 100 rearwardly-facing flange-engaging face 5^a of the supplemental member 5, is depressed by the cartridge-head, and on being so depressed is also moved rearwardly, whereby 105 to provide for this face 5^a engaging the cartridge flange, as g', in the two positions already stated; and to provide that said face 5^a, when once engaged with that flange in its lower position, will continue such engagement while the cartridge moves upwardly 110 and forwardly into the transfer position, Fig. 4. As one suitable manner of providing for that movement of said face 5^a, I preferably arrange the member 5 to have a swinging movement on a pivot or axis, as 6. 115 This form of that member also provides in a favorable way for the proper depression of said member by the cartridge head, as will be evident from Fig. 9.

On firing the gun, the recoil operates 120 through the positive engagement of the member 5 with the head-rim g' to forcibly carry the rearward or leading cartridge X¹ backward with the action-mechanism, and tends to withdraw for an instant the point 125 7 of such leading cartridge away from the head of the next forward cartridge X², so that for the moment a small space may be formed (similarly as shown in Fig. 3) by reason of the suddenness of the recoil and 130

the inertia of the cartridges in the magazine. In some situations, especially when several cartridges are in the magazine and the gun is aimed downwardly, the amount of that open space may be considerable. A normal result following that action is for the magazine spring to drive back the second cartridge and so cause this to strike a sharp blow against the point 7 of said first cartridge, and in some instances this blow, except for the described preliminary inclining of said leading cartridge relatively to the following-cartridge, would be sufficient to fire the primer of said second or following-cartridge X^2 . To prevent that accident is one of the objects of my present improvements and for this purpose among others, I have so organized the mechanism that the said leading or rearward cartridge may be inclined to a safety position and also latched into a positive engagement with the action-bar mechanism, in advance of the firing of the gun. While one cartridge, as X^1 , Fig. 3, is being drawn backwardly as far as the said loading position shown in Fig. 4, a following-cartridge, X^2 , closely follows said first cartridge X^1 and normally bears against the point thereof. And this following movement of said second cartridge X^2 would continue to a more rearward position except for some suitable means whereby to arrest that backward movement of this following cartridge at or just before reaching said loading position. By providing such means,—as for instance, the stop D,—located and operable for so arresting the said following cartridge in that manner, Fig. 3, I avoid the excess-movement backwardly, and the corresponding forward or return movement, which this cartridge X^2 , would otherwise have. Thus the cartridges in the magazine are prevented from having any considerable reciprocatory movement or stroke backwardly and forwardly in the magazine, so that those cartridges now have only the necessary successive rearward movements in the magazine and relatively to the loading position.

Another feature of the operation of the cartridge controlling device and combinations, is the manner in which a cartridge after being detained by the guide-stop device, is released from such detained position while under the pressure of the rearwardly-acting magazine spring and during the forward stroke of the action-mechanism, for thereby driving or impelling the cartridge backwardly against the forwardly moving retraction-engagement devices and to the rearward end of the magazine-tube. By this means two oppositely-acting forces,—the rearwardly-acting momentum of the cartridge and the forwardly-acting momentum of the action-mechanism,—are concentrated or combined, the one against the other, for

thereby quickly and forcibly delivering the said released cartridge to its proper retraction-location in the magazine tube, and for thereby obtaining the maximum power to depress the retraction-member and carry the head-flange of the cartridge into locked engagement therewith. The result of this peculiar mode of action is to locate and retain the cartridge securely in retraction-position, and also in primer-safety position, at or before the instant the sear-lock-retractor operates for releasing the sear, so that the said newly placed cartridge is secured in position fully ready for retraction, (and for elevation or transfer when, later, retracted), before the preceding cartridge then in the barrel, can be fired. Thus the said newly-placed or leading cartridge is safe-guarded by the sear-lock and the action-bar-lock against the shock of firing until such time as this leading cartridge shall have been protected and secured against displacement thereby. For aiding in the accomplishment of these purposes, the sear-lock-retractor is arranged to be held retracted by the main actuator B until the instant after the following-cartridge (X^1 , Fig. 9) has been guided into primer-safety position against the point of the leading cartridge (X^2 , Fig. 2). By this means, also, the shock or impact by the one said cartridge against the other, due to the sudden stopping of the leading cartridge, is delayed until after said primer-safety position of these cartridges is reached.

The timing of the release of the detained cartridge (X^2 , Fig. 8), relatively to and during the forward stroke of the action-mechanism, is regulated by the longitudinal position of the guide-stop faces 10 and 10^a and the location of the rearward end, (see Fig. 9) of the cartridge-lifting guide 8, relatively to the length of said stroke; and by the distance from the rearward end of the magazine-tube. This location of said face 8 is such, in the preferred organization herein illustrated, that this face operates on the forward stroke of the action-mechanism, first to release the detained cartridge (Fig. 9), and later to co-act with the other cartridge-locating means by uplifting the middle portion of the cartridge, thus serving after the manner of a fulcrum whereon to support and offset the cartridge while this is inclined into primer-safety position. The proportionate length of said lifter or guide 8, and the relative locations of this face and of the forward end 8^a, are herein so arranged that said faces or bearings 8 and 8^a come into action for the respective purposes described, in a suitable timing and order of succession. In these operations, in the particular arrangement herein illustrated, said rearward face 8 comes to the cartridge-release position (Fig. 9) while the guide-stop device is in its rearward position and while

the action-mechanism is moving forwardly; and said forward lifting-face 8^a comes into operation, as regards the following-cartridge, when the guide-stop is in its forward position and while the action-mechanism is moving rearwardly, these two operations taking place before the completion of those reverse-strokes, respectively, of the action mechanism, and the guide-stop device D being shifted the distance of its working stroke after the beginning of said operations by a movement concurrent with the terminal-part of the corresponding movements of the action-mechanism.

The action-mechanism is shown as having a working stroke about equal to the length of the cartridge plus the length of the guide-face 10 of the guide-stop, plus the stroke of the guide stop. And in the system of cartridge-placing or cartridge-inclining faces, the initial lifting-face 8^a is located about one cartridge-length from the depressor-face 3, and those faces are located about oppositely to each other relatively to the magazine axis. Also, the stop-face or initial depression face 10^a of the guide-stop D is similarly located relatively to said forward or initial lifting-face 8^a being about opposite thereto relatively to the magazine axis, and, by reason of the mode of operation, in view of the long stroke of the action-mechanism, said forward, lower lifting-face 8^a goes about one cartridge-length forwardly of said upper stop or depression face 10^a , Fig. 1, and then goes rearwardly of that depression-face by about the length of the guide-face 10. Thus the relative forward and rearward positions of those two stop-faces are twice reversed during each complete cycle of their movements. This system of cartridge-inclining guides and stop-faces, thus comprises, in its complete form, those two co-operating but reversely acting cartridge-head-shifting faces 8^a and 10^a ; the two oppositely-disposed guide faces including the upper guide-face 10 and the lower guide-bearing or supporting face 8 located about midway of the length of the leading cartridge X^1 when this is in its initial retraction position, Fig. 1; and the depressor-face or incline 3 at the head of said leading-cartridge, but in some instances some one or more of these details may be modified or omitted, within the scope of my present invention.

A further feature is that when the action-mechanism is in the forward or firing position, the retraction-face 5^a , comes forward to a position under the guide-face 10 of the guide-stop, and is then opposite thereto relatively to the magazine-axis, and then coacts directly with that guide-face 10 and with the depression-face 10^a , and also, in connection with those two faces, coacts with the midway supporting guide-bearing 8 for

thereby first shifting or inclining the leading cartridge into the primer-safety position, and the holding this cartridge securely locked in that position during the firing of a loaded-in cartridge, as indicated in Fig. 1. 70

While the distance transversely of the magazine-axis, (see Fig. 3) between the initial depression face 10^a and the said forward lifting-face 8^a should be less than the diameter of the cartridge head, and while 75 the same relation should also obtain as between the upper guide-face 10 and the lower guide-bearing 8, the passing of this bearing forward of said guide-face and initial depression-face, as in Fig. 9, operates to release the then leading cartridge X^2 , which is thus permitted to assume the retraction-position, as X^1 , as shown in Fig. 2. Thus, on the full forward stroke of the action-mechanism, the pair of faces 8 and 8^a (the guide-bearing and the lifting-face) is carried forward of the guide-stop faces 10 and 10^a while on the full rearward stroke, said pair of faces 8 and 8^a is carried rearward of those guide-stop faces; and thus said pairs of 90 faces reverse their longitudinal position relatively to each other twice during each complete cycle of their movements.

As a further result of those operations, the forward lifting face 8^a comes into alignment during the rearward stroke thereof, with the initial depression-face 10^a , as well shown in Fig. 3, and thus acts to positively intercept the next following cartridge X^2 (as there indicated) thus allowing the direct 100 co-action of the guide-bearing 8, the depressor-guide 3 and the supplement elevator-device 5 (and while this remains in retraction-engagement with the flange g' of the leading cartridge X^1) to upwardly shift the 105 leading cartridge (transversely of the magazine axis) into its initial elevation position (Fig. 4). Thus the upper and lower detent faces 10^a and 8^a are brought into co-action 110 during the middle part of the rearward 115 stroke of the action-mechanism and that co-action is followed at once by the shifting (transversely to its own axis and to the magazine axis) of the leading cartridge from its initial retraction-position (Fig. 2) 120 to its final retraction-position just preceding, Fig. 4, and from a direct control by the retraction-face 5^a and the depressor-face 3, to the direct and positive control of the retraction-face 5^a coacting with the guide 125 130 coming into the head-groove forward of the head-flange g' .

In the operation of the system of cartridge-inclining faces as above explained, the upper and forward depression face 10^a is 125 also a stop-face for a next following cartridge (Fig. 8) when the lower and forward lifting-face 8^a is located forwardly of said depression-face; and, similarly, the lifting-face 8^a is and has the function of a stop- 130

face (Fig. 4) when this face is drawn rearwardly of said initial depression-face 10^a. Thus the upper said face 10^a is a combined depression-face and stop-face, while said lower face 8^a is a combined lifting-face and stop-face. And in the cycle of operations, these two faces, (especially in connection with the guide-bearing 8) operate after the manner of an escapement, for first detaining the following-cartridge (Fig. 7) on one said stop, and later shifting this cartridge for being detained by the other said stop (Fig. 8), and finally releasing the cartridge (Fig. 9) to allow this following-cartridge to take its place as the leading-cartridge at the extreme rearward end of the magazine, Fig. 2. The head of a following-cartridge, as X², shifts downwardly and transversely from the position in Figs. 2 and 3 to about the position shown in Fig. 7, as soon as the lower stop or escapement-face 8^a passes to the rearward of the upper said face 10^a; and the reverse shifting movement occurs when that lower face 10^a passes forward of the upper face 8^a, as shown in Fig. 8, in which the said upper-face 10^a is shown in its rearward position; but the described escapement action does not require the face 10^a to be movable, and if preferred it may be fixedly located, within the purview of my present invention. The movement of the upper escapement-face 10^a serves to change by so much, the point or timing at which, in the cycle of operations, those shifting of the cartridge would otherwise take place. One result of these operations in controlling the following-cartridge, is that during the long rearward stroke of the action-bar, said cartridge nearly follows the movement of the leading-cartridge, and that after the leading-cartridge has been transferred out of the magazine, the following-cartridge goes forwardly only a short distance, and is thus permitted to move rearwardly in and relatively to the magazine during the forward stroke of the action-bar, so that at about the time of release (Fig. 9) said following cartridge has only a short distance to move back under the force of the magazine-spring before reaching its initial retraction-position in Fig. 2; but that release normally occurs (Fig. 9) before the depression-face 10^a has begun to move forward, and while the action-bar is moving rapidly forward, with the result that the cartridge-head is well under the guide-stop D and its said faces before the head-flange meets the oncoming depressible retraction-device 5, so that the full power and momentum of the magazine spring and of the moving cartridges are effectively utilized for depressing that retraction-device and so forcing the head-flange over said retraction-face. Fig. 9 also indicates how the midway bearing-guide 8 is arranged for so co-acting with either of the

cartridge-controlling faces as to release the detained cartridge X², before the action-bar has so far advanced as to engage and operate the movable guide-stop D.

When the cartridges are of suitable proportions and the stroke of the action-mechanism properly corresponds thereto, the guide-stop may in some instances be arranged not to have a reciprocatory or sliding movement; but with cartridges of the style and approximate proportions herein illustrated, I prefer the guide-stop to be arranged for a working stroke of about one-half the length of its guide-face.

When the leading cartridge, as X¹, Fig. 2, has moved fully or nearly to the rearward end of the magazine tube, the middle portion of this cartridge is lifted up by the raised surface or guide-bearing 8, thereby elevating the point 7 of this cartridge above the central primer of the next following cartridge X². At this time if the action-mechanism is forward (Fig. 2) the cartridge-head is guided to the depressed position. If, now, the action-mechanism be partially drawn back, the depressor-guide 3 continues that depression of the head, while the point 7 remains uplifted as before. But when the action-mechanism is drawn farther back, (Fig. 3) the forward end of said cartridge-lifting surface or guide 8 comes into co-action with said guide-stop device D, and for this purpose said guide-bearing 8 is made of extended length and to reach forwardly under the head of a following-cartridge X², when the action-mechanism is forward, as in Fig. 2. Just prior to the time for the withdrawal of the leading-cartridge from its point-contact with the following-cartridge this latter cartridge engages against the forward stop-face 10^a of said guide-stop D, and is thereby initially detained or stopped in its rearward movement.

One feature of the guide-stop device is the relation which the lower or off-setting guide-surface 8 bears to the upper and inclined surface 10^a and to the retraction-face 5^a of the elevator-member 5. When the action-mechanism is near its forward position, these two guide-surfaces are disposed or arranged, about oppositely to each other, and in relative positions to co-act directly with each other and with the adjacent parts for placing the cartridge in an offset and inclined primer-safety position, and also in a positive retraction-engagement with the elevator-device of the action-mechanism. Thus the elevator-device, which is comprised in and is a part of one of the said three mechanism-components, has itself a guide-surface or guide-path 5^b so located and arranged as to co-act with another guide-face, as 10, which is on another of said mechanism-components, whereby to preliminarily locate the cartridge in the primer-safety position ready

for immediate elevation after it has been retracted to the transfer-position below the loading chamber. In this cartridge-locating operation, the said depression-face 10^a operates in advance of the action of the depressor-guide 3 of the main-actuator B, so that the depressor-guide may be said to complete and continue the result or action begun by said depression-face, especially during 5 the period after the rearward movement of the action-mechanism has carried the head-portion of the cartridge rearwardly of said face 10^a. When the guide-stop faces 10 and 10^a have partially depressed and guided 10 the rearwardly moving cartridge head, this head depresses the elevator-member 5 and then by further rearward movement is itself further depressed or held depressed by the depressor-guide 3 already described, and 15 this guide 3 then continues to act for maintaining the primer-safety position of the cartridge after this has been carried farther back toward the transfer position. Another 20 feature of this organization of the said mechanism-components, results from the stroke of the action-mechanism whereby the guide-stop device co-acts first, while the action-mechanism is forward, with the magazine-guide-surface 8^a for locating and 25 engaging the head of the leading cartridge, and later, when this mechanism is rearward, 30 co-acts directly with different magazine guide-surfaces adjacent to the point of the leading cartridge, and thus serves for stopping the next following cartridge. Thus 35 said guide-stop device operates at successive times in different combinations, for effecting successive and different results.

For inserting cartridges into the magazine through the entrance passage, which is 40 normally closed against the exit of the cartridges by the loading door 52, the operator inserts the point of a cartridge through the space 52^a in the end of said loading door 45 and thereby catches the point of the cartridge back of the spring follower 51,—when all of the cartridges are exhausted,—or back of a cartridge head, as the case may be, and then by crowding forward on the 50 cartridge being inserted, the said follower,—or the cartridge in lieu thereof,—may be crowded forward in the magazine, while the loading door moves upwardly a short distance for permitting the newly inserted cartridge 55 to be pushed forward entirely within the magazine. When a cartridge is thus inserted after the magazine has been entirely emptied, the spring follower 51 will, of course, immediately push the said cartridge 60 rearwardly into the position for being engaged with the elevator device of the action-mechanism, whereupon a second cartridge may be inserted forwardly of such rearward cartridge, by pushing forward the 65 spring-follower as above indicated. In this

manner the magazine may be replenished from time to time as desired, substantially as described in said prior Patent No. 963,171. In practice, the width and proportions of the loading door, and also of the point-entrance 70 52^a therein, may, of course, be varied in accordance with the requirements in any given instance, to properly correspond with the sizes and proportions of the cartridges which are to be used in the firearm.

During the earliest stage of the recoil-actions or forces, the action-bar lock, as 75 36, operates to delay the movements which are normally imparted by those recoil forces to the cartridges in the magazine-tube, and when the recoil-action has proceeded somewhat further, thereby unlocking the action-bar, the later stages of the recoil-actions naturally tend, by reason of the inertia of the frame and the momentum of the action-mechanism, to cause the latter to move quickly backward relatively to and substantially free of restraint by the frame. Thus 80 the cartridge engaging devices in the magazine-tube are relieved from further interference (during that rearward stroke) from the said disturbing forces, which then will have become effective in substantial part for assisting in carrying forward at the proper instant, the normal operation of the action-mechanism. Thus the action-bar-lock and the means for operating the same 85 from the movements of co-acting parts, (including the inertia member 37), and from the recoil, (as more fully set forth in my 90 said prior patent) are here made to directly coöperate with the said retraction-engagement devices and with the guide-stop device for regulating and timing the action of those members and combinations, and thereby 95 secure completeness and reliability of 100 operation in all respects.

Having thus described my invention, I 105 claim:—

1. In a fire-arm, the combination, with a 110 breech-block arranged for forward and rearward movements, and with a block-operating magazine action-bar also arranged for forward and rearward movements, of a main elevator-member carried on the action-bar and having a cartridge-lifting face movable upwardly on its working stroke, and a supplemental elevator carried on the main elevator and having a flange-engaging face movable upwardly and forwardly during 115 the upward working stroke of said supplemental elevator relatively to the main elevator-member.

2. In a fire-arm, the combination, with a 120 breech-block arranged for forward and rearward movements, and with a block-operating magazine action-bar also arranged for forward and rearward movements, of a main elevator-member carried on the action-bar and having a cartridge-lifting face movable 125

upwardly and rearwardly on its working stroke, and a supplemental elevator carried on the main elevator and having a flange-engaging face arranged for moving upwardly 5 and forwardly during the upward working stroke of said supplemental elevator relatively to the main elevator-member.

3. In a fire-arm, the combination, with a breech-block arranged for forward and 10 rearward movements, and with a block-operating magazine action-bar also arranged for forward and rearward movements, of a main elevator-member carried on the action-bar and having a cartridge-lifting face movable 15 upwardly and rearwardly on its working stroke, and a supplemental elevator pivotally-supported near its forward end on the main elevator and having at its rearward end a flange-engaging face movable up- 20 wardly and forwardly during the upward working stroke of said supplemental elevator relatively to said main elevator-member.

4. In a fire-arm, the combination, with a 25 breech-block arranged for forward and rearward movements, and with a block-operating magazine action-bar also arranged for forward and rearward movements, of a main elevator-member pivotally supported in the 30 action-bar and having a cartridge-lifting-face movable upwardly and rearwardly on its working stroke, and a supplemental elevator pivotally-supported near its forward end on the main elevator, and having at its 35 rearward end a flange-engaging face movable upwardly and forwardly during the upward working stroke of said supplemental elevator relatively to said main elevator-member, whereby said flange-engaging face 40 may first move upwardly and forwardly and afterward upwardly and rearwardly, substantially as described.

5. In a fire-arm, the combination, with a frame having a loading chamber therein, 45 and with a breech-block slidable in said chamber, of a slidable block-operating action-bar having a magazine-tube and provided with a fixed cartridge-head guide located substantially in alinement with the 50 front end of the breech-block when this block is being operated forwardly by the action-bar, a main elevator device carried by the action-bar and located for transferring the cartridge from the magazine into 55 the loading-chamber, and a spring-actuated elevator device carried on and supplemental to the main elevator device and depressible by the rearwardly moving cartridge and located for partially elevating the leading cartridge when this is freed from point-pressure, into engagement with the fixed head-guide of the action-bar.

6. In a fire-arm, the combination, with a frame having a loading chamber therein,

and with a breech-block slidable in said chamber, of a slidable block-operating action-bar having a magazine-tube and provided with a fixed cartridge-head guide located substantially in alinement with the front end of the breech-block when this 70 block is being operated forwardly by the action-bar, a main elevator device carried by the action-bar and located for transferring the cartridge from the magazine into the loading-chamber, and a combined elevator and retraction device carried on and supplemental to the main elevator device and located for elevating the leading cartridge when this is freed from point-pressure, into engagement with the fixed head-guide of the action-bar.

7. In a fire-arm, the combination, with a frame having a loading chamber therein, and with a breech-block slidable in said chamber, of a slidable block-operating action-bar having a magazine-tube and provided with a fixed cartridge-head guide located substantially in alinement with the front end of the breech-block when this 85 block is being operated forwardly by the action-bar, a main elevator device carried by the action-bar and located for transferring the cartridge from the magazine into the loading-chamber, and a spring-actuated combined elevator and retraction device 90 pivotally-supported on and supplemental to the main elevator device and depressible by the rearwardly moving cartridge and located for elevating the leading cartridge when this is freed from point-pressure, into 95 engagement with the fixed head-guide of the action-bar.

8. In a fire-arm, the combination, with a breech-block mechanism arranged for forward and rearward movements and having 105 on the face of the breech-block cartridge-head-engaging guides, of a slidable block-operating action-mechanism having a magazine provided with a cartridge outlet opening and having a cartridge-head guide located in alinement with said guides of the breech-block when the block-mechanism is being operated forwardly by the action-mechanism, and having a compound cartridge retractor-elevator operatively mounted in the action mechanism and located and arranged for first engaging the leading cartridge in the magazine when this is forward and next retracting such cartridge with the action-mechanism when this moves rearwardly; actuator-means comprised in said compound retractor-elevator and arranged for operating one member relatively to the other member thereof, and actuator-means located in the firearm in position for operating the retractor-elevator, whereby to elevate the retracted cartridge first into engagement with said magazine guide and finally 110 115 120 125

- into engagement with said breech-block guides by the successive operation of the members of the compound retractor-elevator.
9. In a fire-arm, the combination, with breech-block mechanism arranged for forward and rearward movements and having on the face of the breech-block cartridge-head-engaging guides, of a slideable block-operating action-mechanism having a magazine provided with a cartridge outlet opening and having a cartridge-head guide located in alinement with said guides of the breech-block when the block-mechanism is being operated forwardly in unison with the action-mechanism; and having a cartridge retractor-elevator comprising a main member elevatably-supported in the action mechanism below said outlet-opening, and a supplemental member movably-supported on said main member in position for engaging a cartridge in the magazine when this is forward and then retracting such cartridge with the magazine when this moves rearwardly, and for afterward partially elevating the cartridge for engaging the head-flange thereof with said magazine cartridge guide, and actuator means for operating said main elevator-member for transferring the partially elevated cartridge to the front of the breech-block.
10. In a fire-arm, in combination, a frame and a breech-block mechanism, a magazined action-mechanism carrying a cartridge engaging-and-retracting elevating device, actuator-means for operating said cartridge elevating-device, and a cartridge-detent located on the frame and operable from the action-mechanism, and arranged for detaining a following-cartridge while the cartridge-retracting-elevating device withdraws the leading cartridge out of point-contact with said following-cartridge and into position for elevation to the breech-block mechanism.
11. In a firearm, the combination, with a frame having therein a loading-chamber, and with a breech-block mechanism, of a magazined action-mechanism carrying a cartridge engaging-and-retracting elevating member, actuator-means for operating said cartridge elevating-member, and a cartridge-detent device located on the frame forward of the loading-chamber and shiftably forwardly and rearwardly from the action-mechanism, and in position for detaining a following-cartridge while the cartridge retractor-elevating member withdraws the leading cartridge out of point-contact with said following-cartridge, whereby the said leading cartridge while in retraction-engagement with said elevating member is transferred out of the magazine toward the loading chamber.
12. In a fire-arm, the combination, with a frame and with a breech-block mechanism,
- of a magazined action-bar carrying a cartridge engaging-and-retracting elevating member, actuator-means for operating said cartridge elevating-member, and a reciprocatory cartridge-detent device located on the frame and operable by the action-bar movement, and in position for detaining a following-cartridge while the cartridge-retracting-elevating member withdraws the leading cartridge out of point-contact with the following-cartridge, whereby the said leading cartridge while in retraction-engagement with said elevating member is transferred out of the magazine toward the breech-block mechanism free of point-contact.
13. In a fire-arm, the combination, with a frame and with a breech-block mechanism, of a magazined action-bar carrying a cartridge engaging-and-retracting elevating member, actuator-means for operating said cartridge elevating-member, and a sliding cartridge-detent device located on the frame and for operation by the action-bar in the direction of the action-bar movement, and having these movements arranged and timed for terminating coincidentally; and having said detent device located in position for detaining a following-cartridge while the cartridge-retracting-elevating member withdraws the leading cartridge out of point-contact with the following-cartridge, whereby the said leading cartridge while in retraction-engagement with said elevating member is transferred out of the magazine toward the breech-block mechanism free of point-contact.
14. In a fire-arm, the combination, with a breech-block mechanism arranged for forward and rearward movements and having on the face of the breech-block cartridge-head-engaging guides, of a block-operating action-mechanism having a magazine provided with a cartridge outlet opening and having a cartridge-head guide in alinement with said guides of the breech-block when the block-mechanism is being operated forwardly by the action-mechanism, and having a cartridge-retractor-elevator comprising a main member pivotally mounted in the action mechanism at a point rearwardly of the said outlet opening, and a supplemental elevator member pivotally supported on said main member in position for engaging the leading cartridge in the magazine when this is forward and then retracting such cartridge with the magazine when this moves rearwardly, actuator means for operating said elevator members, and a stop device located for intercepting a following-cartridge before said leading cartridge reaches the elevation-position, whereby to free the leading cartridge from point-pressure and then transfer this cartridge into engagement with said breech-block guides.
15. In a breech-loading fire-arm having a

- slidable action-mechanism provided with a magazine tube, and having a breech-block operated forwardly by engagement with the action-mechanism, the combination with a 5 main cartridge-transfer-member carried by the action-mechanism and having a working stroke transversely of the direction of movement of the action-mechanism, an actuator located and operable for moving said main 10 transfer-member through its working stroke on the forward movement of the action-mechanism, and a supplemental transfer-member operatively-supported on said main transfer-member and depressible by the 15 head of a cartridge moving rearwardly in the magazine tube, and located in position for engaging forward of the head-flange of a cartridge when this is in the longitudinal position for being transferred from the rear- 20 ward end of the magazine-tube to the front of the breech-block.
16. In a breech-loading fire-arm having a slidable action-mechanism provided with a magazine tube, and having a breech-block 25 operated forwardly by engagement with the action-mechanism, the combination with a main cartridge-transfer-member elevatably-supported in the action-mechanism and having its working stroke transversely of the 30 direction of movement of the action-mechanism, an actuator located and operable for moving said main transfer-member through its working stroke on the forward movement of the action-mechanism, and a depressibly-supported supplemental transfer-member carried on said main transfer-member in position for engaging forward of the head-flange of a cartridge when this is in the longitudinal position for being transferred 35 from the rearward end of the magazine-tube to the front of the breech-block.
17. In a fire-arm, the combination, with a frame having a loading chamber therein, and with a breech-block slidable in said 40 chamber, of a slidable block-operating action-mechanism having a magazine-tube and provided with a depressor-guide inclined downwardly and rearwardly for initially depressing the cartridge-head and located at 45 its upper end substantially in alinement with the front end of the breech-block when this block is being operated forwardly by the action-mechanism, a main elevator device carried by the action-mechanism and having the main lifting-face located forwardly of the cartridge-head for transferring the cartridge from the magazine into the loading-chamber, and a spring-actuated supplemental elevator device carried on the 50 main elevator device and having a spring-pressure lifting-face located rearwardly of said main lifting-face and in position and operable for bearing upwardly against the depressed cartridge head, before the upward 55 movement of said main lifting face, whereby the depressed cartridge is preliminarily elevated by said spring-pressure applied to the cartridge-head, is next further elevated by the concurrent action of said two lifting faces, and is then fully elevated by the continued action of said main lifting face bearing against the cartridge forwardly of the head thereof. 60
18. In a fire-arm, the combination, with a frame having a loading chamber therein, and with a breech-block slidable in said chamber, of a slidable block-operating action-bar having a magazine-tube and provided with a depressor-guide inclined downwardly and rearwardly for initially depressing the cartridge-head, and located at its upper end substantially in alinement with the front end of the breech-block when this block is being operated forwardly by the action-bar; a main elevator device carried by the action-bar and having the main lifting-face located forwardly of the cartridge-head, actuator-means arranged for operating said main elevator device through the working stroke required for transferring the cartridge from the magazine to the face of the breech-block in the loading-chamber, and a spring-actuated supplemental elevator de- 65

vice pivotally-supported on the main elevator device by a pivot located near its forward end, and depressible by a swinging movement on said pivot by said depressor-guide acting through a cartridge head, and having a spring-pressure lifting-face located rearwardly of said main lifting-face and also rearwardly of said pivot and in position and operable to bear upwardly against the depressed cartridge head, whereby the depressed cartridge is preliminarily elevated by said spring-pressure lifting-face applied to the cartridge head during the upward swinging movement of the pivotally-supported supplemental elevator device relatively to the main elevator device, is next further elevated by the concurrent action of said two lifting faces, and is then fully transferred to the loading chamber by the continued action of said main lifting face.

20. In a fire-arm, the combination, with a frame having a loading chamber therein, and with a breech-block slidable in said chamber, of a slidable block-operating action-bar having a magazine-tube and provided with a depressor-guide inclined downwardly and rearwardly for initially depressing the cartridge-head, and located at its upper end substantially in alinement with the front end of the breech-block when this block is being operated forwardly by the action-bar; a main elevator device pivotally-supported in the action-bar mechanism at a point rearwardly of the depressor-guide; and having the main lifting face located forwardly of the cartridge-head; actuator-means arranged for swinging said main elevator-device upwardly on its pivot for transferring the cartridge from the magazine to the face of the breech-block in the loading-chamber; and, a spring-actuated supplemental elevator device movably-supported on the swinging main elevator device and having a spring-pressure lifting-face located rearwardly of said main lifting-face and in position and operable to bear upwardly against the cartridge head, whereby the cartridge is preliminarily elevated by said spring-pressure lifting-face, is next further elevated by the concurrent action of said two lifting faces, and is then fully elevated by the continued swinging upward-working stroke of said main lifting face bearing against the cartridge forwardly of the head.

30. The front end of the breech-block when this block is being operated forwardly by the action-bar; a main elevator device pivotally-supported in the action-bar mechanism at a point rearwardly of the depressor-guide; and having the main lifting face located forwardly of the cartridge-head; actuator-means arranged for swinging said main elevator-device upwardly on its pivot for transferring the cartridge from the magazine to the face of the breech-block in the loading-chamber; and, a spring-actuated supplemental elevator device movably-supported on the swinging main elevator device and having a spring-pressure lifting-face located rearwardly of said main lifting-face and in position and operable to bear upwardly against the cartridge head, whereby the cartridge is preliminarily elevated by said spring-pressure lifting-face applied to the cartridge head, is next further elevated by the concurrent action of said two lifting faces, and is then fully elevated by the continued swinging, upward-working stroke of said main lifting face.

40. In a fire-arm, the combination, with a frame having a loading chamber therein, and with a breech-block slidable in said chamber, of a slidable block-operating action-bar having a magazine-tube and provided with a depressor-guide inclined downwardly and rearwardly for initially depressing the cartridge-head and located at its upper end substantially in alinement with the front end of the breech-block when this block is being operated forwardly by the action-bar; a main elevator device pivotally-supported in the action-bar mechanism at a point rearwardly of the depressor-guide; and having the main lifting face located forwardly of the cartridge-head; actuator-means arranged for swinging said main elevator-device upwardly on its pivot for transferring the cartridge from the magazine to the face of the breech-block in the loading-chamber; and, a spring-actuated supplemental elevator device movably-supported on the swinging main elevator device and having a spring-pressure lifting-face located rearwardly of said main lifting-face and in position and operable to bear upwardly against the cartridge head, whereby the cartridge is preliminarily elevated by said spring-pressure lifting-face applied to the cartridge head, is next further elevated by the concurrent action of said two lifting faces, and is then fully elevated by the continued swinging, upward-working stroke of said main lifting face.

50. In a fire-arm, the combination, with a frame having a loading chamber therein, and with a breech-block slidable in said chamber, of a slidable block-operating action-bar having a magazine-tube and provided with a depressor-guide inclined downwardly and rearwardly for initially depressing the cartridge-head and located at its upper end substantially in alinement with the front end of the breech-block when this block is being operated forwardly by the action-bar; a main elevator device pivotally-supported in the action-bar mechanism at a point rearwardly of the depressor-guide; and having the main lifting face located forwardly of the cartridge-head; actuator-means arranged for swinging said main elevator-device upwardly on its pivot for transferring the cartridge from the magazine to the face of the breech-block in the loading-chamber; and, a spring-actuated supplemental elevator device movably-supported on the swinging main elevator device and having a spring-pressure lifting-face located rearwardly of said main lifting-face and in position and operable to bear upwardly against the cartridge head, whereby the cartridge is preliminarily elevated by said spring-pressure lifting-face applied to the cartridge head, is next further elevated by the concurrent action of said two lifting faces, and is then fully elevated by the continued swinging, upward-working stroke of said main lifting face.

60. In a fire-arm, the combination, with a frame having a loading chamber therein, and with a breech-block slidable in said chamber, of a slidable block-operating action-bar having a magazine-tube and provided with a depressor-guide inclined downwardly and rearwardly for initially depressing the cartridge-head and located at its upper end substantially in alinement with the front end of the breech-block when this block is being operated forwardly by the action-bar; a main elevator device pivotally-supported in the action-bar mechanism at a point rearwardly of the depressor-guide; and having the main lifting face located forwardly of the cartridge-head; actuator-means arranged for swinging said main elevator-device upwardly on its pivot for transferring the cartridge from the magazine to the face of the breech-block in the loading-chamber; and, a spring-actuated supplemental elevator device movably-supported on the swinging main elevator device and having a spring-pressure lifting-face located rearwardly of said main lifting-face and in position and operable to bear upwardly against the cartridge head, whereby the cartridge is preliminarily elevated by said spring-pressure lifting-face applied to the cartridge head, is next further elevated by the concurrent action of said two lifting faces, and is then fully elevated by the continued swinging, upward-working stroke of said main lifting face.

tion-bar; a main elevator device pivotally-supported in the action-bar at a point rearwardly of the depressor-guide and having the main lifting face located forwardly of the cartridge-head; actuator-means arranged for swinging said main elevator-device upwardly on its pivot for transferring the cartridge from the magazine to the face of the breech-block in the loading-chamber; and, a spring-actuated supplemental elevator device pivotally-supported on the swinging main elevator device by a pivot located near its forward end, and depressible by a swinging movement on said pivot by said depressor-guide acting through a cartridge-head, and having a spring-pressure lifting-face located rearwardly of said main lifting-face and in position and operable to bear upwardly against the cartridge head, whereby the cartridge is preliminarily elevated by said spring-pressure lifting-face, is next further elevated by the concurrent action of said two lifting faces, and is then fully elevated by the continued swinging upward-working stroke of said main lifting face bearing against the cartridge forwardly of the head.

22. In a breech-loading fire-arm having a slidable action-mechanism provided with a magazine tube and having a depressor-guide at the rearward end of said tube, the combination with a main cartridge-transfer-member carried by the action-mechanism, an actuator located and operable for moving said main transfer-member through its working stroke on the forward movement of the action-mechanism, a combined retraction and transfer-member supported on and supplemental to said main transfer-member, and located in position for engaging forward of the head-flange of a cartridge when this is in the longitudinal position for being transferred out of the magazine-tube, and a loading-door located forward of said cartridge-transfer members and having a portion of its upper surface extending higher than the lower side of the tube for co-acting with the depressor-guide and with said supplemental transfer member in locating the rearward cartridges in position ready for transferring out of the magazine, substantially as described.

23. In a breech-loading fire-arm having a slidable action-mechanism provided with a magazine tube and having a depressor-guide at the rearward end of said tube, the combination with a main cartridge-transfer-member carried by the action-mechanism, an actuator located and operable for moving said main transfer-member through its working stroke on the forward movement of the action-mechanism, a combined retraction and transfer-member supported on and supplemental to said main transfer-member, and located in position for engag-

ing forward of the head-flange of a cartridge when this is in the longitudinal position for being transferred out of the magazine-tube, a loading-door located forward of said cartridge-transfer members, a cartridge-lifting inclined face at the forward end of the loading-door, and a cartridge-detaining stop located for co-acting with said cartridge-lifting face and operable from the movements of the action-mechanism, for first detaining and later releasing a cartridge which follows the leading cartridge.

24. In a fire-arm, the combination with the frame having a mechanism chamber and a magazine below the barrel of the arm, and with a block-mechanism comprising a reciprocatory block, a firing-member reciprocatable in the block, a sear arranged for engaging the retracted firing-member, a sear-lock arranged for locking and releasing the sear while this engages the retracted firing-member, and a combined sear-lock-retractor and action-bar-lock; of a shiftable guide-stop located adjoining the rearward end of the barrel and shiftable longitudinally thereof; and a combined block-operating and guide-stop-operating action-bar having therein the rearward part of the magazine and operatively-supported in position for engaging the firing-member, and arranged for having a working stroke continuing rearwardly after the completion of the rearward stroke of the block for thereby retracting the firing-member into the sear-engaging position, and arranged for having its forward stroke continuing after the completion of the forward stroke of the block for thereby shifting the guide-stop forwardly after the block reaches its forward position, and having an actuator-face in position for engaging and retracting the sear-lock-retractor before the beginning of the rearward stroke of the block, and for only releasing the sear-lock-retractor after the guide-stop has been shifted forward subsequently to the completion of the forward stroke of the block.

25. In a firearm, the combination with the frame having a mechanism chamber and a magazine below the barrel of the arm, and with a block-mechanism comprising a reciprocatory block, a firing-member reciprocatable in the block, a sear arranged for engaging the retracted firing-member, a sear-lock arranged for locking and releasing the sear while this engages the retracted firing-member, and a combined sear-lock-retractor and action-bar-lock; of a sliding guide-stop located adjoining the rearward end of the barrel and slidable longitudinally thereof; and a combined block-operating and guide-stop-operating action-bar having therein the rearward part of the magazine and operatively-supported in position for engaging the firing-member, and arranged

for having a working stroke continuing rearwardly after the completion of the rearward stroke of the block for thereby retracting the firing-member into the sear-engaging position, and arranged for having its forward stroke continuing after the completion of the forward stroke of the block for thereby sliding the guide-stop forwardly after the block reaches its forward position, and having an actuator-face in position for engaging and retracting the sear-lock-retractor before the beginning of the rearward stroke of the block, and for only releasing the sear-lock-retractor after the guide-stop has been slid forwardly subsequently to the completion of the forward stroke of the block.

26. In a firearm, the combination with the frame having a mechanism chamber and a magazine below the barrel of the arm, and with a block-mechanism comprising a reciprocatory block, a firing-member reciprocatable in the block, a sear arranged for engaging the retracted firing-member, a sear-lock arranged for locking and releasing the sear while this engages the retracted firing-member, and a combined sear-lock-retractor and action-bar-lock; of a shiftable guide-stop located adjoining the rearward end of the barrel and shiftable longitudinally thereof, said guide-stop comprising the upper guide-face and a depression-face; a combined block-operating and guide-stop-operating action-bar having therein the rearward part of the magazine and operatively-supported in position for engaging the firing-member, and arranged for having a working stroke continuing rearwardly after the completion of the rearward stroke of the block for retracting the firing-member into the sear-engaging position, and for having its forward stroke continuing after the completion of the forward stroke of the block for thereby shifting the guide-stop forwardly after the block reaches its forward position, and having an actuator-face in position for engaging and retracting the sear-lock-retractor before the beginning of the rearward stroke of the block, and for only releasing the sear-lock-retractor after the guide-stop has been shifted forwardly subsequently to the completion of the forward stroke of the block, and a depressible retraction-face located in position in the action-bar for coacting with said upper guide-face and thereby locking a cartridge in retraction-engagement with the action-mechanism before the unlocking of the sear.

27. In a firearm, the combination with the frame having a mechanism chamber and a magazine below the barrel of the arm, and with a block-mechanism comprising a reciprocatory block, a firing-member reciprocatable in the block, a sear arranged for engaging the retracted firing-member, a

sear-lock arranged for locking and releasing the sear while this engages the retracted firing-member, and a combined sear-lock-retractor and action-bar-lock; of a shiftable 5 guide-stop located adjoining the rearward end of the barrel and shiftable longitudinally thereof, said guide-stop comprising the upper guide-face and a depression-face; a combined block-operating and guide-stop 10 operating action-bar having therein the rearward part of the magazine and operatively-supported in position for engaging the firing-member, and arranged for having a working stroke continuing rearwardly after 15 the completion of the rearward stroke of the block for retracting the firing-member into the sear-engaging position, and for having its forward stroke continuing after the completion of the forward stroke of the 20 block for thereby shifting the guide-stop forwardly after the block reaches its forward position, and having an actuator-face in position for engaging and retracting the sear-lock-retractor before the beginning of 25 the rearward stroke of the block, and for only releasing the sear-lock-retractor after the guide-stop has been shifted forwardly subsequently to the completion of the forward 30 stroke of the block; a depressor-face inclining downwardly and rearwardly and located at the rearward end of the magazine; a compressible retraction-face located in position in the action-bar for coacting with 35 said upper guide-face and with said inclined depressor-face, and a cartridge-inclining guide-bearing in the magazine forward of said retraction-face, whereby to place a cartridge in the inclined primer-safety position and in retraction engagement with the action-mechanism, and with the head-flange of the cartridge contiguous to said depressor-face, before the unlocking 40 of the sear.

28. In a firearm, the combination with the frame having a mechanism chamber and a magazine below the barrel of the arm, and with a block-mechanism comprising a reciprocal block, a firing-member reciprocal in the block, a sear arranged for engaging the retracted firing-member, a sear-lock arranged for locking and releasing the sear while this engages the retracted firing-member, and a combined sear-lock-retractor and action-bar-lock; of a shiftable guide-stop located adjoining the rearward end of the barrel and shiftable longitudinally thereof, said guide-stop comprising the upper guide-face and a depression-face; a combined block-operating and guide-stop 45 operating action-bar having therein the rearward part of the magazine and operatively-supported in position for engaging the 50 firing-member, and arranged for having a working stroke continuing rearwardly after the completion of the rearward stroke of the block for retracting the firing-member into the sear-engaging position, and for having 55 its forward stroke continuing after the com-

pletion of the forward stroke of the block for thereby shifting the guide-stop forwardly after the block reaches its forward position, and having an actuator-face in position for engaging and retracting the sear-lock-retractor before the beginning of the rearward stroke of the block, and for only releasing the sear-lock-retractor after the guide-stop has been shifted forwardly subsequently to the completion of the forward 70 stroke of the block; a depressor-face inclining downwardly and rearwardly and located at the rearward end of the magazine; a compressible retraction-face located in position in the action-bar for coacting with 75 said upper guide-face and with said inclined depressor-face, and a cartridge-inclining guide-bearing in the magazine forward of said retraction-face, whereby to place a cartridge in the inclined primer-safety position and in retraction engagement with the action-mechanism, and with the head-flange of the cartridge contiguous to said depressor-face, before the unlocking 80 of the sear.

29. In a machined action-mechanism breech-loading firearm, the combination with a frame having therein a mechanism chamber, and with a sear-lock block-mechanism reciprocatable through a working 90 stroke forwardly and rearwardly in said chamber, and provided with a sear-lock-retractor, of a combined block-actuator and sear-lock-retractor actuator comprised in the action-mechanism and reciprocatable 95 through a working stroke in excess of the reciprocatory stroke of the block-mechanism, and arranged for having the forward stroke continuing after the completion of the forward stroke of the block-mechanism, 100 and having an actuator-face located for engaging and retracting the sear-lock-retractor throughout the working stroke of the block-mechanism and only releasing said sear-lock-retractor during the excess forward stroke of the action-mechanism after 105 the completion of the forward stroke of the block-mechanism, and a shiftable guide-stop located in position for being operated forwardly by the action-mechanism during and by the said excess forward stroke of the action-mechanism, whereby the sear-lock-actuator is held retracted until after the guide-stop has been shifted forwardly subsequently to the completion of the forward 110 stroke of the block-mechanism.

30. In a magazined action-mechanism breech-loading firearm, the combination with a frame having therein a mechanism chamber, and with a sear-lock block-mechanism reciprocatable through a working 115 stroke forwardly and rearwardly in said chamber, and provided with a sear-lock-retractor, of a combined block-actuator and sear-lock-retractor actuator comprised in 120 the action-mechanism and reciprocatable 125 through a working stroke in excess of the reciprocatory stroke of the block-mechanism, and arranged for having the forward stroke continuing after the completion of the forward stroke of the block-mechanism, 130 and having an actuator-face located for engaging and retracting the sear-lock-retractor throughout the working stroke of the block-mechanism, and only releasing said sear-lock-retractor during the excess forward stroke of the action-mechanism after the completion of the forward stroke of the block-mechanism.

the action-mechanism and reciprocatable through a working stroke in excess of the reciprocatory stroke of the block-mechanism, and arranged for having the forward stroke continued after the completion of the forward stroke of the block-mechanism, and having an actuator-face located for engaging and retracting the sear-lock-retractor throughout the working stroke of the block-mechanism and only releasing said sear-lock-retractor during the excess forward stroke of the action-mechanism after the completion of the forward stroke of the block-mechanism; a movable guide-stop located in position for being operated forwardly by the action-mechanism, and for operating on a cartridge in the magazine during the said excess forward stroke of the action-mechanism, and a cartridge retractor-elevator having a retraction-face located for engaging with the cartridge during that excess forward stroke, whereby the sear-lock-retractor is held retracted until after the operation of the guide-step and until the retraction-face has engaged with the rearward cartridge in the magazine.

31. In a magazined action-mechanism breech-loading firearm, the combination with a frame having therein a mechanism chamber, and with a sear-lock block-mechanism reciprocatable through a working stroke forwardly and rearwardly in said chamber, and provided with a sear-lock-retractor, of a combined block-actuator and sear-lock-retractor actuator comprised in the action-mechanism and reciprocatable through a working stroke in excess of the reciprocatory stroke of the block-mechanism, and arranged for having the forward stroke continued after the completion of the forward stroke of the block-mechanism, and having an actuator-face located for engaging and retracting the sear-lock-retractor throughout the working stroke of the block-mechanism and only releasing said sear-lock-retractor during the excess forward stroke of the action-mechanism after the completion of the forward stroke of the block-mechanism; a slidable guide-stop located in position for being slid forwardly by the action-mechanism, and for operating on a cartridge in the magazine, during the said excess forward stroke of the action-mechanism, and a retractor-elevator having a retraction-face located for engaging with the cartridge during that excess forward stroke, whereby the sear-lock-actuator is held retracted until after the sliding forward of the guide-stop, and until the retraction-face has engaged with the rearward cartridge in the magazine.

32. In a magazined action-mechanism breech-loading firearm, the combination with a frame having therein a mechanism chamber, and with a sear-lock block-mech-

nism reciprocatable through a working stroke forwardly and rearwardly in said chamber, and provided with a sear-lock-retractor, of a combined block-actuator and sear-lock-retractor actuator comprised in the action-mechanism and reciprocatable through a working stroke in excess of the reciprocatory stroke of the block-mechanism, and arranged for having the forward stroke continuing after the completion of the forward stroke of the block-mechanism, and having an actuator-face located for engaging and retracting the sear-lock-retractor throughout the working stroke of the block-mechanism and only releasing said sear-lock-retractor during the excess forward stroke of the action-mechanism after the completion of the forward stroke of the block-mechanism, a shiftable guide-stop comprising a guide-face and a depression-face and located in position for being shifted forwardly by the action-mechanism during and by the said excess forward stroke of the action-mechanism, a compound cartridge retractor-elevator comprising a depressible member having a retraction-face located for engaging a leading cartridge during said excess forward stroke of the action-mechanism, and a cartridge-inclining guide-bearing located forward of the retraction-face and in position for coacting with said depression-face for first detaining, next releasing and then inclining a cartridge, whereby to place the leading-cartridge in primer-safety position and in locked engagement with the retraction-face before the release of the sear-lock-retractor, and to hold the sear-lock-retractor in its retracted position until after the guide-stop has been shifted forwardly subsequently to the completion of the forward stroke of the block-mechanism.

33. In the magazined action-mechanism breech-loading firearm, the combination with a frame having therein a mechanism chamber, and with a sear-lock block-mechanism reciprocatable through a working stroke forwardly and rearwardly in said chamber and provided with a sear-lock-retractor, of a combined block-actuator and sear-lock-retractor actuator comprised in the action-mechanism and reciprocatable through a working stroke in excess of the reciprocatory movement of the block-mechanism, and having the forward stroke continuing after the completion of the forward stroke of the block-mechanism, and having an actuator-face located for engaging and retracting the sear-lock-retractor throughout the working stroke of the block-mechanism and only releasing said sear-lock-retractor during the excess forward stroke of the action-mechanism after the completion of the forward stroke of the block-mechanism, a shiftable guide-stop comprising

ing a guide-face and a depression-face and located in position for being shifted forwardly by the action-mechanism during and by the said excess forward stroke of the 5 action-mechanism, a cartridge retractor-elevator comprising a compressible member having a retraction-face located for engaging a leading cartridge during said excess forward stroke of the action-mechanism, and 10 a pair of cartridge-inclining faces comprising the midway guide-bearing and the forward lifter-face both located forward of the retraction-face and in position for coacting with said guide-stop faces for first detaining, next releasing and then inclining a leading cartridge, and detaining and inclining the next following cartridge, whereby to place these two cartridges in primer-safety relative positions, and to place the 20 leading cartridge in locked engagement with the retraction-face before the release of the sear-lock-retractor, and to hold the sear-lock-retractor in its retracted position until after the guide-stop has been shifted forwardly subsequently to the completion of 25 the forward stroke of the block-mechanism.

34. In a magazined action-mechanism fire-arm, the combination with the frame having 30 therein a mechanism chamber, and with a breech-block mechanism reciprocatable in said chamber, of a guide stop located forward of said chamber and having a guide-face and forward thereof having an initial depression-face, a slidale magazined block-operating action-bar arranged for having a stroke longer than a cartridge, a retrector-elevator carried in the action-bar and having a retraction-face located in opposition 40 to said guide-face when the action-bar is in its forward position, and a pair of cartridge-inclining faces located within the magazine and consisting of a forward lifting-face and a midway guide-bearing, which 45 are both located and arranged forward of the guide-stop when the action-bar is in its forward position, and are also arranged for both to pass rearwardly of said initial-depression face when the action-bar is drawn back to the rearward end of its stroke, substantially as described.

35. In a magazined action-mechanism fire-arm, the combination with the frame having therein a mechanism chamber, and 55 with a breech-block mechanism reciprocatable in said chamber, of a guide-stop located forward of said chamber and having a guide-face and forward thereof having an initial-depression-face, a slidale magazined block-operating action-bar arranged for having a stroke longer than a cartridge, a retrector-elevator carried in the action-bar and having a retraction-face located in opposition to said guide-face when the action-bar 60 is in its forward position, and a cartridge-

inclining midway guide-bearing located within the magazine forward of the retraction-face and also located forward of the guide-stop when the action-bar is in its forward position, said retraction-face and the 70 guide-bearing being arranged for both to pass rearwardly of said guide-stop when the action-bar is drawn back to the rearward end of its stroke, substantially as described.

36. In a magazined action-mechanism 75 fire-arm, the combination with the frame having therein a mechanism chamber, and with a breech-block mechanism reciprocatable in said chamber, of a guide-stop located forward of said chamber and having the 80 initial-depression-face, a slidale magazined block-operating action-bar arranged for having a stroke longer than a cartridge, a retrector-elevator carried in the action-bar and having a compressible retraction-face 85 located in opposition to said guide-stop and rearwardly of said depression-face when the action-bar is in its forward position, and a pair of cartridge-inclining faces located within the magazine, and consisting of a 90 forward lifting-face and a midway guide-bearing, which are both located and arranged forward of the guide-stop when the action-bar is in its forward position, and are also arranged for both to pass rearwardly of said initial-depression face when the action-bar is drawn back to the rearward end of its stroke, whereby said depression-face and said lifting-face operate as an escape- 95 ment for detaining, shifting and releasing a 100 cartridge next following the leading-cartridge, substantially as described.

37. In a magazined action-mechanism fire-arm, the combination with the frame having therein a mechanism chamber, and 105 with a breech-block mechanism reciprocatable in said chamber, of a guide-stop located forward of said chamber and having a guide-face and forward thereof having an initial-depression face; a slidale magazined 110 block-operating action-bar arranged for having a stroke longer than a cartridge; a retrector-elevator carried in the action-bar and having a spring-actuated compressible retraction-face located in opposition to said 115 guide-face and rearwardly of said depression-face when the action-bar is in its forward position, and a pair of cartridge-inclining faces located within the magazine and consisting of a forward lifting-face and a midway guide-bearing, which are both located and arranged forward of the guide-stop when the action-bar is in its forward position, and are also arranged for both to pass rearwardly of said initial-depression 120 face when the action-bar is drawn back to the rearward end of its stroke, substantially as described.

38. In a magazined action-mechanism fire-arm, the combination with the frame 125

- having therein a mechanism chamber, and with a breech-block mechanism reciprocatable in said chamber, of a guide-stop located forward of said chamber and having the upper guide-face and forward thereof having the initial-depression face, a slideable magazine block-operating action-bar arranged for having a stroke longer than a cartridge, a retractor-elevator carried in the action-bar and having a spring-actuated depressible retraction-face located in opposition to said guide-face and rearwardly of said depression-face when the action-bar is in its forward position; a pair of cartridge-inclining faces located within the magazine and consisting of a forward lifting-face and a mid-way guide-bearing, which are both located and arranged forward of the guide-stop when the action-bar is in its forward position, and are also arranged for the guide-bearing to pass rearwardly of said guide-stop when the action-bar is drawn back to the rearward end of its stroke, and a depressor-face located at the rearward end of the magazine rearward of the retraction-face and in position for coacting with said retraction-face in locating and holding the head of a cartridge, substantially as described. 5
39. In a breech-loading action-mechanism firearm, the combination with a frame having therein a mechanism chamber, and with a breech-block mechanism reciprocatable in said chamber, of a block-operating action-bar comprised in the action-mechanism; a reciprocatory firing-member carried in the block-mechanism and having a firing-pin arranged for its point to project through the front of the breech-block when the firing member is in its forward position in said block; a sear arranged for engaging the firing-member when this is retracted; a sear-lock located and arranged in the block-mechanism for locking the sear in engagement with the retracted firing-member; a sear-lock-retractor located and arranged for retracting the sear-lock when the breech-block and action-mechanism are both in the firing position; a sear-lock-retractor actuator-face located on the action-bar in position for retracting the sear-lock-retractor and for only releasing the said sear-lock-retractor on a continued forward movement of the action-mechanism after the placing of the breech-block mechanism in the firing position; a cartridge detent device movably located and arranged on the frame for operation by the action-bar and for depressing the head of a cartridge in the magazine; a combined cartridge retractor and elevator comprised in the action-mechanism and arranged for retraction-engagement with the leading cartridge after this has been depressed by the said depression device, and elevator actuating means in position in the frame for operating the cartridge elevator upwardly during the forward stroke of the action-mechanism, whereby the said sear-lock-retractor lever is maintained in a retracted position during the operation upwardly of the cartridge elevator, and whereby the firing-member is held thus sear-locked until after the movable depression-device has been moved forwardly by a continued forward movement of the action-bar after the block-mechanism is advanced to the firing position. 10
40. In a breech-loading action-mechanism firearm, the combination with a frame having therein a mechanism chamber, and with a breech-block mechanism reciprocatable in said chamber, of a block-operating action-bar comprised in the action-mechanism; a reciprocatory firing-member carried in the block-mechanism; a sear arranged for engaging the firing-member when this is retracted; a sear-lock rotatably-supported in the block-mechanism in position for locking the sear in engagement with the retracted firing-member; a sear-lock-retractor consisting of a lever pivotally-supported in the breech-block in position for retracting the sear-lock when the breech-block and action-mechanism are both in the firing position; a lever-actuating face on the action-bar in position for retracting said lever sear-lock-retractor, and for only releasing this retractor on the forward movement of the action-mechanism after the placing of the breech-block mechanism in the firing position; a cartridge depression device movably located and arranged on the frame for operation by the action-bar and for depressing the head of a cartridge in the magazine; a combined cartridge retractor and elevator comprised in the action-mechanism and arranged for retraction-engagement with the leading cartridge after this has been depressed by the said depression device, and elevator actuating means in position in the frame for operating the cartridge elevator upwardly during the forward stroke of the action-mechanism, whereby the said sear-lock-retractor lever is maintained in a retracted position during the operation upwardly of the cartridge elevator, and whereby the firing-member is held thus sear-locked until after the movable depression-device has been moved forwardly by a continued forward movement of the action-bar after the block-mechanism is advanced to the firing position. 15
41. In a breech-loading action-mechanism fire-arm, the combination with a frame having therein a mechanism-chamber, and with a magazined action-bar reciprocatable in said chamber, of a retractor-elevator opera- 20

tively supported in the action-bar at the rearward end thereof and having a retraction-face operatively-supported in position for engaging the head-flange of a leading-
 5 cartridge, a combined depression-face and initial stop-face carried on the frame in a position forward of said retraction-face when the action-mechanism is in its forward position, and arranged for depressing
 10 the head of a rearwardly-moving leading-cartridge into position for first operating and next locking with the said retraction-face, and a cartridge-inclining guide-bearing located in the magazine in a position
 15 forward of said retraction-face and also forward of said depression-face when the action mechanism is in its forward position, and arranged for elevating the point of said leading cartridge while the head thereof is
 20 being first depressed and later engaged with the retraction - face, substantially as described.

42. In a breech-loading action-mechanism fire-arm, the combination with a frame having therein a mechanism-chamber, and with a magazined action-bar reciprocatable in said chamber, of a retractor-elevator operatively supported in the action-bar at the rearward end thereof and having a spring-actuated
 25 retraction-face operatively-supported in position for engaging the head-flange of a leading-cartridge, and a combined depression-face and initial stop-face carried on the frame in a position forward of said re-
 30 traction-face when the action-mechanism is in its forward position, and arranged for depressing the head of a rearwardly-moving leading-cartridge into the position for first operating and next locking with the
 35 said retraction-face, and a cartridge-point elevating guide-bearing located in the magazine in a position forward of said retraction-face and also forward of said depression-face when the action mechanism is in its
 40 forward position, and arranged for elevating the point of said leading cartridge while the head thereof is being first depressed and later engaged with the retraction-face, substantially as described.

50 43. In a breech-loading action-mechanism fire-arm, the combination with a frame having therein a mechanism-chamber, and with a magazined action-bar reciprocatable in said chamber, of a retractor-elevator operatively supported in the action-bar at the rearward end thereof and having a spring-
 55 operated depressible retraction-face in position for engaging the head-flange of the leading-cartridge, and a movable guide-stop
 60 having a guide-face and a combined depression-face and initial stop-face, said guide-stop being carried on the frame in a position in which its said depression-and-stop face is above and forward of said retraction-
 65 face when both the action-mechanism and

the guide-stop are in their forward position, and arranged for depressing the head of a rearwardly-moving leading cartridge into the position for first depressing and next locking with the said retraction-face, substantially as described. 70

44. In a breech-loading action-mechanism fire-arm, the combination with a frame therein having a mechanism-chamber, and with a magazined action-bar reciprocatable 75 in said chamber, of a retractor-elevator operatively supported in the action-bar at the rearward end thereof and having a spring-actuated retraction - face operatively - supported in position for engaging the head-flange of the leading-cartridge, and a movable guide-stop having a guide-face and a combined depression-face and initial stop-face, said guide-stop being carried on the frame in a position in which said depression- 80 and-stop face is above and forward of said retraction-face when both the action-mechanism and the guide-stop are in their forward position, and arranged for depressing the head of a rearwardly-moving leading- 85 cartridge into the position for first operating and next locking with the said retraction-face, and a cartridge-inclining means located in the magazine in a position forward of said retraction-face and also forward of said depression-and-stop face when the action mechanism is in its forward position, substantially as described. 90

45. In a breech-loading action-mechanism fire-arm, the combination with a frame having therein a mechanism chamber, and with a reciprocatable block-mechanism retractable in said chamber, of a slideable block operating magazined action-bar comprised in the action-mechanism, a cartridge stop located 100 on the frame forward of said chamber and having a depression-face in position for transversely shifting the head of a cartridge passing rearwardly in the magazine, and a combined cartridge-elevator and cartridge- 105 retractor operatively supported in the action-bar at the rearward end thereof, in position for delivering a retracted cartridge to the front of the retracted block-mechanism, and having a retractor-face located 110 rearwardly of the cartridge-stop and oppositely of the magazine-axis relatively to said stop, and arranged for retractively-engaging the head-flange of a cartridge after this has passed rearwardly of and under said depression-face. 115

46. In a breech-loading action-mechanism fire-arm, the combination with a frame having therein a mechanism chamber, and with a reciprocatable sear-lock block-mechanism 120 retractable in said chamber and comprising a sear-lock-retractor, of a slideable block-operating magazined action-bar comprised in the action-mechanism, a cartridge-inclining depression-face located on the frame for 125 130

- ward of said mechanism-chamber and above the magazine axis, a retractor-elevator operatively-supported in the action-bar in position for delivering a retracted cartridge to the front of the retracted block-mechanism, and having a retraction-face located below the magazine and rearwardly of said depression-face in position for retraction-engagement with the head-flange of a cartridge after this has passed rearwardly in the magazine and under said depression-face, and sear-lock-retractor retracting-means operatively intermediate to the block-mechanism and the retractor-elevator, substantially as described.
47. In a breech-loading action-mechanism fire-arm, the combination with a frame having therein a mechanism-chamber, and with a block-mechanism reciprocatable in said chamber, of a magazined block-operating action-mechanism reciprocatable in said chamber, a retraction-elevator operatively supported in the action-mechanism at the rearward end thereof and having a spring-actuated retraction-face in position for engaging the head-flange of the leading-cartridge, and a system of five cartridge-inclining and holding faces located two of them supported on the frame and three of them in the action-mechanism along the magazine, said frame-supported-faces comprising a forward depression-face, and said magazine faces comprising a forward lifting-face, a midway guide-bearing, and a depressor-face which is located in the rearward end of the magazine in position for direct co-action with said upper guide-face when the action-mechanism is in its forward position, whereby the leading cartridge is shifted into an inclined position relatively to the axis of the magazine and with the cartridge head depressed, and whereby the head of the next following cartridge is elevated by the said forward lifting-face; thereby placing these two cartridges in oppositely-disposed inclinations relatively to the magazine axis, and relatively to each other in primer-safety positions, substantially as described.
48. In a breech-loading action-mechanism fire-arm, the combination with a frame having therein a mechanism-chamber, and with a block-mechanism reciprocatable in said chamber, of a magazined block-operating action-mechanism reciprocatable in said chamber, a retractor-elevator operatively-supported in the action-mechanism at the rearward end of and below the magazine, and having a retraction-face in position for engaging under the head-flange of a cartridge, and a system of four cartridge-inclining and holding faces located two of them supported on the frame and two of them in the action-mechanism along the magazine and both forwardly of the retractor-elevator, said frame-supported-faces comprising a forward depression-face, and said magazine faces comprising a forward lifting-face and a midway guide-bearing which is located in position for coacting with said frame-supported faces for first detaining and for releasing a cartridge when the action-mechanism during its forward movement come nearly to its forward position, whereby the leading cartridge and the next following cartridge are placed relatively to each other in primer-safety positions, substantially as described.
49. In a breech-loading action-mechanism fire-arm, the combination with a frame having therein a mechanism-chamber, and with a block-mechanism reciprocatable in said chamber, of a magazined block-operating action-mechanism reciprocatable in said chamber, a retractor-elevator operatively-supported in the action-mechanism at the rearward end of and below the magazine, and having a retraction-face in position for engaging under the head-flange of a leading cartridge, elevator-actuating means arranged for actuating the elevator and transferring leading-cartridge out of the magazine to the block-mechanism on each forward reciprocatory movement of the action-mechanism, and a plurality of cartridge-controlling means located along the magazine forward of the retractor-elevator and arranged for successively changing the relations and coaction during the successive reciprocations, respectively, of the action-mechanism, of some of those controlling means relatively to others of them, and thereby detaining, releasing and primer-safety-placing, in succession a series of cartridges during the successive reciprocations, respectively, of the action-mechanism.
50. In a firearm of the class herein described having a slidable action-mechanism provided with a magazine-tube, and provided with a fixed-flange-guide, in combination, a plurality of cartridge-locating faces comprising a lifter-face and guide-faces located and arranged for first placing the spring driven leading-cartridge and a following cartridge in primer-safety position, a retractor-elevator device having two members initially operative in succession and arranged for engaging the leading-cartridge and thereby hold this cartridge in a fixed location in the action-mechanism during the early portion of the rearward stroke thereof, a cartridge-stop located for detaining the following-cartridge after the leading-cartridge in moving rearwardly has arrived under the loading chamber of the firearm; a spring actuator engaging and arranged for operating one member of the retractor-elevator for partially elevating the head of the leading cartridge instantly upon such detaining of the following-cartridge, during the lat-

ter portion of the rearward stroke of the action-mechanism, and thereby engage the flange of the leading-cartridge with said flange-guide of the action-mechanism; and, 5 a positively-operating actuator arranged for engaging and operating the other member of the retractor-elevator during the early part of the next following forward stroke of the action-mechanism.

10 51. In a firearm having a slidable breech-block and having a block-operating action-bar provided with a magazine, the combination with a fixed flange-guide located on the action-bar in position for alining the 15 cartridge with the breech-block face, of a plurality of head-guiding faces on the action-bar and in position for holding the cartridge-head lowered below said fixed flange-guide and rearward of the transfer-position, and a retractor-elevator co-acting with said head-guiding faces for retracting the cartridge while the head thereof is in such lowered and rearward position, and for afterward guiding the cartridge-head into engagement with said fixed flange-guide, and 25 elevator-means located and operable for transferring the cartridge from such flange-guide engagement to the face of the breech-block.

30 52. In a breech-loading firearm having a slidable action-mechanism provided with a magazine tube having an outlet side-opening at the rearward end of said tube, the combination with a main cartridge-transfer-member carried by the action-mechanism opposite to said outlet opening, actuator-means located for operating said main transfer-member for delivering a cartridge through said outlet-opening on the forward 35 movement of the action-mechanism, a retraction-transfer member supported on and supplemental to said main transfer-member, and located in position for engaging forward of the head-flange of a cartridge 40 when this is in the longitudinal position for being transferred out of the magazine-tube, a cartridge-lifting guide-surface located in the magazine-tube forward of said cartridge-transfer members, and a movable 45 guide-stop device operable by the action-mechanism and located for co-acting with said cartridge-lifting guide-surface and also located and adapted for guiding the cartridge-head into engagement with said retraction-transfer member when the action-mechanism is near its forward position.

53. In a breech-loading firearm having a

frame with a loading-chamber therein and having a slidable action-mechanism provided with a magazine tube having an outlet side-opening at the rearward end of said tube, the combination with a main cartridge-transfer-member carried by the action-mechanism opposite said outlet opening, actuator-means located for operating said main transfer-member for delivering a cartridge through said outlet-opening into the loading-chamber on the forward movement of the action-mechanism, a retraction-transfer member supported on and supplemental to said main transfer-member, and located in position for engaging forward of the head-flange of a cartridge when this is in position for being transferred out of the magazine-tube, a cartridge-lifting guide-surface located in the magazine-tube forward of said cartridge-transfer member, and a sliding guide-stop device carried on the frame forward of the loading-chamber and operable from the action-mechanism, and located in position for co-acting with said retraction-transfer member when the action-mechanism is forward, and for co-acting with the forward end of said cartridge-lifting guide-surface when the action-mechanism is drawn back to the transfer position.

54. In a fire-arm, the combination, with a slidable breech-block mechanism having on the face of the breech-block a cartridge-head-engaging guide, of a slidable block-operating action-mechanism having a magazine provided with a cartridge outlet opening and having a cartridge-head guide located in alinement with said guides of the breech-block when the block-mechanism is being operated forwardly by the action-mechanism, a cartridge retractor-elevator pivotally supported in the action mechanism and having a depressible retractor-face located in position and arranged below the magazine for engaging a leading cartridge in the magazine when this is forward, and for then retracting such cartridge with the magazine when this moves backwardly, and for elevating the cartridge first into full engagement with said magazine guide and later into partial engagement with said breech-block guide.
